TYPEWRITING CALCULATING MACHINE

Clair D. Lake, Binghamton, and Francis E. Hamilton, Endicott, N. Y., assignors to International Business Machines Corp., New York, N. Y., a corporation of New York

Application November 24, 1939, Serial No. 305,792

26 Claims. (Cl. 235—59)

1

This invention relates to combined typewriting and calculating machines.

The main object of the invention is to provide, in combination with a typewriter, means for automatically multiplying factors typed on a sheet and controlling the automatic typing of the product, preferably as an extension of the factors on the same line of the sheet as the line on which the factors were typed. Thus, a quantity of articles may be typed as one factor on a line of a sheet, the unit price of the article as a second factor, automatic multiplication of the two factors, as a result of their typing, will occur, and the product will be automatically typed on the same line of the sheet in an extension field of the same.

It is intended to start multiplying operation automatically as a consequence of the typing of the last or units order digit of the second factor.

It is further intended to type the product in a predetermined extension section, and to require both the multiplying operation to be completed and the first column of the predetermined section to be brought to typing position in order to initiate an automatic readout of the multiplying means and typing of the product into said section.

It is also a purpose of the invention to distinguish between debits and credits by providing for automatic typing of the debits in one predetermined extension section of a sheet and the automatic typing of the credits in another predetermined extension section of the sheet. To condition the machine for typing a credit product in the predetermined credit extension section of the sheet, a credit key is operated and, under control thereof, the automatic typing of the product into the debit extension section is prevented, while, at the same time, the automatic typing of the product is delayed until the credit extension section is brought to typing position.

An object of the invention also is to provide a totalizer for totaling the debits and credits automatically typed in the extension sections and, preferably, to control entry of the amounts into the totalizer by the automatic typing of the amounts. One advantage of this is that any error in the balance standing on the totalizer may be checked back as an error in the typed extensions.

It is also an object automatically to type the balance standing on the totalizer into a predetermined total section of a sheet and to provide for the balance to be typed either on the same

2

line as the last extension amount or on the next line.

The invention also provides novel value retaining means to receive the digits typed in succession on the sheet and to retain the value until it is read out either into the totalizer or the multiplying means. The novel value retaining means is in the form of a bank of value relay coils and related contacts which are selectively closed to represent, by their positions, the typed value. The multiplying means and the totalizer are of the cycling type, and a feature of the invention is that the digits may be typed and the value retained without requiring a cycle for each digit, and that after all the digits have been typed, the multiplying means or the totalizer may be cycled to receive the value set up in the value retaining means. The multiplying means and the totalizer comprise accumulator wheels which receive different extents of movement corresponding to different magnitudes of values, and differentially operating means converts the positional value representation of the value retaining means into differentially timed equivalents to determine the extents of movement of the accumulator wheels.

The negative amounts; in this instance, the credits, are entered as complements into the totalizer. When the negative amounts exceed the plus or debit amounts, the totalizer carries the complement of the negative balance. It is a feature of the invention that the negative balance may be automatically typed as a true number into the total section of the sheet under control of the totalizer carrying the complement of the negative balance.

Another purpose of the invention is to provide for the entry of a discount item, involving multiplication of a typed discount percentage by the typed amount on which the discount is to be taken. The discount percentage is typed on the bill sheet and entered in the multiplying means as a factor 1000 times greater than its actual value; thus 2.5%, equal to 2.5/100 is typed and entered as 25. This factor is multiplied by the amount on which the discount is made and the product then obtained is 1000 times greater than the true discount. The invention provides for conversion of this false product into the true product by reducing the false product by three decimal places to the left, equivalent to dividing the false product by 1000, and reading out and typing the true product. Stated generally, the above involves the entry of a factor into the multiplying means as a number of different magnitude and

the reading out of the product in true denominational order relation, just as though the factor had been entered in its original denominational order form into the multiplying means. One advantage of this feature of the invention is that a multiplying means limited to a predetermined number of denominational orders may serve for multiplying a number which includes a fraction of the lowest or units order by another factor and then reading out the product in true decimal place relation. In this connection, means are provided to round out the lowest unit order of the product by adding "1" thereto when the next lowest denominational order reads "5" or more.

The invention also provides for the automatic resetting of the multiplying means after the product has been read out therefrom and typed. Alternative means are provided to initiate resetting of the multiplying means at will, and such means causes the value retaining means to be restored to unactuated or zero condition and to interrupt multiplying operation in the event multiplication has not yet been completed.

It is also a purpose of the invention to provide an error key control to prevent further entry into the value retaining means of the digits of the factors as they are typed, and also to clear the value retaining means of the value setting effected prior to discovery of the error. A feature of the error key control is that credit controls for causing a product to be typed as a credit value may be rendered ineffective and the product typed, instead, as a debit amount.

The invention also provides for the multiplying operation of two factors of an item to take place during the typing of matter on the sheet which does not enter into the calculation; for example, a description of the item.

The invention further provides for alternatively automatically resetting or not resetting the totalizer after its balance has been read out and typed.

The machine provides for the elimination of the typing of zero standing in orders of the totalizer or the product (multiplying) bank, when such zeros are not preceded by a significant figure and, instead, causing a letter spacing of the sheet to bring the next column thereof to typing position. The number of effective denominational orders of the totalizer or product bank correspond to the number of columns of the extension section of the sheet into which the value on a bank is to be typed, with each effective order of a bank corresponding to one of the extension columns. It is a further object of the invention to vary the number of effective orders of a bank of value manifesting means in accordance with the number of columns in the extension section into which the value in the bank is to be typed. Thus, the product bank and the totalizer bank may have a maximum number of denominational orders corresponding to a maximum number of columns in an extension section. If the three highest orders of the bank read "0," then letter spacing is controlled thereby to space the corresponding extension columns past the typing position. The invention provides for reduction of the number of effective orders of a bank in order to suppress the letter spacing operations normally controlled by the eliminated orders, whereby the first effective order of the bank corresponds to the first column of a reduced extension field and the value in the latter order is typed into the latter column. Thus, if a bank has eight orders and the extension section has eight columns, if the

three highest orders read "0," then letter spacing occurs to bring the fifth column of the extension section to typing position. If the product or total is not to exceed five orders, and the extension sections, correspondingly, are provided only with five columns, the three highest orders of an eight order bank always read "0" and if suppression of the letter spacing operations under control of the highest orders were not effected, the correlation between the fifth order of the bank and the corresponding highest order column of the reduced extension field would be destroyed. By means of the present invention, when column reduction is desired, the letter spacing under control of the three highest orders of a bank is suppressed. Further, the invention provides for corresponding reduction of the columns of the value retainer bank.

Among still other objects of the invention is the provision of means for automatically effecting carriage return and line spacing operation as an incident following the automatic typing of a product or total into an extension section, and for automatically effecting tab spacing operation between the dollars and cents orders of an automatically typed extension.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a plan view of the machine,

Fig. 2 is a side view of a selector switch of the machine,

Fig. 3 is a vertical section through the product bank of the machine, taken along lines 3-3 of Fig. 1,

Figs. 11a and 11b are time charts showing extensive accumulator cycles and readout cycles,

Figs. 12a to 12f constitute the circuit diagram, and

Fig. 13 shows an illustrative bill prepared by the machine.

Fig. 14 is a perspective view showing the carriage return mechanism.

The bill

Fig. 13 shows an illustrative bill which may be prepared by the machine. The bill sheet has the usual heading area to receive the heading and, below the heading area, has the item area to receive lines of items. The item area is divided into vertical fields, which, reading from left to right, are the code number field (Lot No.), the quantity field (QU), the dollars orders field of the Price section, the tens and units cents orders field of the Price section, the Description field, the dollars field of the Amount section, the cents orders field of the Amount section, the dollars field of the Credit section, the cents field of the

Credit section, the dollars field of the Total section, and the cents field of the Total section. The Amount section, in the present instance, receives debit amounts and may be referred to also as the debit section. The Amount, Credit, and Total sections may also be referred to as the extension sections for receiving extensions of the data typed in the quantity and price sections. The heading is typed within a portion of the heading area which is a vertically upward extension of the description field. The heading area may thus be considered as part of the description field.

The bill items may be debit or credit items. For example, the first item of the illustrative bill is a computed debit. The second item is a computed discount credit, the next five items are computed debits, the eighth item is a computed credit, the ninth, tenth, and eleventh items are successively computed discount credits, the successive discounts being taken on the successive balances, and the last item is a simple credit, not involving computation of values in the quantity and price columns. The net balance is typed below the last item line.

Brief plan of operation

As seen in Fig. 1, the machine comprises a typewriter unit TU and a calculator unit CU, electrically connected, through wires gathered in a cable 8, for interrelated operations.

The tab stops are set in the typewriter in accordance with the spacing of the vertical fields of the bill. Each such field is brought to typing position by operation of the tab key of the typewriter. Thus, repeated operations of the tab key bring the description field of the bill to typing position, and the operator types the heading. Following the typing of the heading, a carriage return operation is effected and the bill vertically spaced to position the first item line at the typing line. The lot number field is then tabularly spaced to typing position and the lot number of the article involved in the first item typed in this field. In succession, the quantity, price, and description fields are tabularly spaced to typing position and the quantity, price, and description of the first item typed. During the typing of the quantity and price, they are entered as multiplier and multiplicand factors in a value retaining means. When the right-hand or units order digit of the price has been entered, multiplying means comes into operation to multiply the two factors. The multiplication proceeds during the typing of the description and may be completed either before or after the amount section of the bill is tabulated to typing position. When multiplication is completed, the value retaining means is cleared of the factors, and, with the amount section also tabulated to typing position, automatic readout means comes into play to read out the product of the quantity and price factors and cause the product to be automatically typed by the typewriter keys into the columns of the amount section. During the automatic readout and typing of the product, the value retaining means is again set up to represent the product. After the product has been typed, an automatic carriage return operation occurs and, in the interval between the completion of the typing of the product and the bringing of the quantity field of the next line to typing position, the product is read out of the value retaining means into a totalizer. This totalizer accumulates debit and credit items and the balance standing therein may be read out into the total section of the bill, such

total or balance read out being initiated by operation of a total key.

It should be noted that if the customer is to be debited with a known sum, the entry of this sum may be effected by entering "1" into the quantity section and the sum in the price section. The product of these two factors is the sum itself, which would be automatically typed in the amount section and entered in the totalizer in the same manner as any other debit product.

In entering a computed credit item, such as shown in line 8 of the bill, the quantity and price factors are entered in the same manner as for a debit product. But before tabulating the bill after 15 the typing of the description, the operator depresses a credit key. This prevents the automatic typing of the extension or product into the amount section of the bill and permits the computed credit to be automatically typed only into the credit section of the bill when tabulated to typing position. After the auto typing of the credit and as a result of the previous depression of the credit key, the credit is automatically entered subtractively, as a complement, into the 20 totalizer.

In entering a simple credit, one not involving multiplication, the operator tabulates the bill to the credit section, depresses the credit key, and manually types the credit amount which is entered subtractively into the totalizer. When dealing with a discount item, such as in line 2 of the bill, the discount percentage is typed into the quantity section, with the tens order of the discount percentage being typed in the hundreds or first column of the quantity field, the units order in the tens column, and the decimal equivalent of the fraction in the units column. The amount on which the discount is to be figured is then typed into the price section. Multiplication proceeds, as before, during the typing of the description. Before tabulating to the Amount section, the operator depresses a discount key, after which the bill is tabulated further to the credit section. Under control of the discount key, the product is reduced by three decimal places to the left and automatically typed as a credit into the credit section, and then subtractively entered into the totalizer. When the discount percentage is to be taken on the balance standing in the totalizer, as in line 9, the operator, during the entry of the preceding item in line 8 and before the amount section of the bill is tabulated to typing position, depresses a total key. This prevents automatic carriage return, and when the bill is tabulated to the total section, the balance is automatically read out from the totalizer and typed on line 8 into the total section. The operator then manually initiates carriage return and incidental line spacing and proceeds with the typing of line 9 in the manner explained for the other discount item (line 2), using the balance, typed in the total section of the preceding line, as the price value on which the discount is to be taken. The advantage of printing the balance for discount purposes is particularly evident when the totalizer is of the concealed type, the reading of which is not visible to the operator.

After the last item has been printed, the operator depresses the total key, types in the description, and tabulates the bill to the total field, into which the net balance is automatically entered from the totalizer. The operation of the total key does not cause resetting or zeroizing of the totalizer, so that the net balance may be carried forward to a next bill to the same customer.

However, when the balance is not to be carried forward, the operator, instead of depressing the total key, depresses a total and reset key, which not only causes printing of the balance but also resetting of the totalizer.

The bill sheet shown in Fig. 13 has an eight digit capacity in each of the amount, credit, and total sections. This allows for the typing of a product in the amount and credit sections obtained by multiplying a quantity factor of three digits by a price factor of five digits, of which the product cannot exceed eight digits. The totalizer capacity is limited to eight orders and a total or balance of eight digits may be typed into the total section.

In some transactions, the quantity factors of each item do not exceed two digits and the price factors do not exceed three digits, so that their product cannot exceed five digits. Further, in such transactions, the total of the items may never exceed five digits or always be below \$1000.00. For such transactions, a bill sheet containing only five columns in each of the amount, credit, and total sections will be used, and the tab stops will be set according to the spacing between the reduced extension sections. The quantity and price sections will not be reduced in size since a discount item would still require the typing of three quantity digits and a five order amount to be discounted. The product or the discount cannot, however, exceed five digits, as the product of the three discount percentage digits and the five amount digits would be reduced by three decimal places to the left to give the true discount amount.

In order to provide for the automatic typing of the extensions in the proper columns of the reduced extension fields of the bill, column reduction means is provided, rendered effective by manual operation of a column reduction switch. The column reduction means, in effect, reduces the capacity of the value retaining means, the product readout means, and the total readout means from eight orders to five.

In the following parts of the description, a common reference character may be used to denote similar elements, and the elements may be differentiated by suffixing a distinguishing character to the common character, with a hyphen between the characters. Thus, the typewriter keys (Figs. 1 and 9) have the common reference character 10, and keys 10-1, 2 . . . 8 refer to the keys for causing typing of the digits 1, 2, . . . 8.

The typewriter unit

Referring to Figs. 1 and 9, the typewriter unit TU is of a well known kind, the general principles of which may be found in Patents Nos. 1,777,056 and 1,873,512. Depression of a key 10 releases a latch 11 from a cam 12, permitting the cam to be forced by a lever 13 against a friction roller 14 constantly rotated by the typewriter motor. As cam 12 engages the roller 14, it is rocked together with its carrier 15 in a direction to depress the connected link 16. This link, through linkage 17, propels the type bar 18 against the sheet on platen 19, thereby typing the character corresponding to the operated key. Towards the end of the stroke of the type bar, it strikes a universal member 20 which, through a link 21, actuates the escapement control 22 to cause an intraline or character spacing operation of the typewriter carriage 23. Operation of the space bar SP also causes a similar intraline spacing.

The carriage return means includes a key CR depression of which initiates automatic action of the carriage return mechanism, which may be of the kind disclosed in Patents No. 1,753,450, No. 2,200,767, and No. 1,955,614. The carriage return key CR (see Fig. 14) is pivoted on the rod 431 (also see Fig. 9) and has an arm 462c controlling a cam unit 463 which is generally similar to the cam unit including cam 12 but includes only a single-lobe cam 464. The friction clutch 465 is substantially identical with the one described in Patent No. 1,753,450 which, when engaged, causes a tape drum 466 to be rotated in such wise as to wind up the carriage return tape 467. This tape passes over a guide roller 468 and thence under the member 439 to a pulley 469 mounted on one arm of a bell crank 470. The bell crank is pivotally mounted on a bracket 471 secured to member 439 which is part of carriage 23 (Fig. 9). The arm of the crank carrying pulley 469 extends downwardly through an opening in member 439. After passing around pulley 469, the tape is secured to the underside of member 439.

25 The clutch 465 is controlled by the toggle links 472 which interconnect a relatively fixed bracket 473 and a clutch operating lever 474. One of the toggle links has an arm 472a connected by a link 475 to cam unit 463. When the carriage 30 return key CR is depressed, the cam 464 is operatively engaged by the periphery of power roller 14, whereby the cam unit is rotated in a direction to depress link 475. This action of the link 35 straightens the toggle linkage 472 and moves it slightly past dead center position. The straightening of the toggle linkage causes the upper end of the lever 474 to move to the right to render clutch 465 active. An adjustable plate 476 limits the movement of the toggle linkage 472 past 40 dead center position in which the linkage is held by a spring 477.

Cooperating with the arm 472a is one arm of a bell crank 478 pivotally mounted on a fixed member 479. The other arm of the bell crank is connected by a rod 480 to one arm of a three-armed lever 481 pivotally mounted on a fixed part of the framework. One of the other arms of lever 481 is connected by a link 482 to a trip lever 483 pivotally mounted on the real rail 442 (see also Fig. 9). The trip lever 483 has an inclined surface 483a designed to act as a cam surface. Secured in the end plate 438 of the carriage 23 (Fig. 9) is the marginal stop rack 485 on which the right and left-hand margin stops 24a and 24, 55 respectively, are adjustably mounted.

When the carriage return key CR is depressed to bring clutch 465 into action, lever 478 is rocked counterclockwise (Fig. 14). This causes link 482 to move downwardly and to the right, thereby 60 rocking lever 483 in a direction to raise cam surface 483a into the path of the downwardly projected part 424 of the left margin stop 24. The clutch 465 when engaged causes the tape 467 to draw the carriage 23 to the right (Fig. 14) and when part 424 of stop 24 strikes cam surface 483a of lever 483, and rocks this lever in a clockwise direction this causes the link 482 to be drawn to the left with the result that lever 478 is rocked clockwise and the arm thereof cooperating with the arm 472a will bend the toggle linkage 72 to effect disengagement of clutch 465.

The carriage is arrested in left-hand margin position by the engagement of the projection 424 of stop 24 with the lug 483a formed in the usual tabular lever 488 forming part of the tabulatin-

mechanism such as disclosed in Patent No. 1,935,436. The platen 19 is line spaced each time the carriage return mechanism is operated. The means by which this is accomplished is described in detail in Patent No. 1,957,322. Briefly, when lever 470 is rocked counterclockwise (Fig. 14) by tape 461 just before the actual carriage return movement begins, the lever, through a tongue and slot connection, depresses a slide 403. This slide carries a pivoted dog 404 which engages the usual line space ratchet 405 (see Fig. 1). Thus, each time the slide 403 is depressed, dog 404 acts on ratchet 405 to turn platen 19 through one line space increment. The setting of the usual line space control lever 406 governs the extent of a line spacing movement as explained fully in Patent No. 1,957,322.

The tab spacing means is of the automatic type, such as disclosed in Patent No. 1,935,436, and includes the tab key Tab, depression of which initiates automatic action of the tabular spacing mechanism to effect tab spacing in accordance with the setting of the tab stops (not shown). The tab stops are set in accordance with the required lateral spacing of the lists or vertical fields of the bill (Fig. 13) to be prepared.

Peculiar to the present invention is a normally open switch 24 (see Fig. 10) mounted on the frame behind the carriage 23. An extension 25' of the left margin stop 25 closes the switch when the carriage is returned to the beginning of the line.

The carrier 15 of each of the digit keys has an insulating roller 26 for engaging the adjacent spring blade 27, upon operation of the digit key, 35 to close inner and outer contacts 28 and 28' in succession. Similarly, depression of the space bar, the carriage return key, and the tab key causes closure of an associated pair of contacts 28.

A solenoid 30 is associated with each digit key, 40 the carriage return key, the tab key, and the space bar. Energization of a solenoid 30 acts through linkage 31 to depress the associated element automatically.

The typewriter unit also is provided with an error key EK, a credit key CK, a discount key DK, a total key TK, and a total and reset key TRK, each closing contacts which are shown in the circuit diagram, Fig. 12a.

Also included in the typewriter unit, in addition to the usual typewriter motor switch SW-T, are the three-pole switch SW-L, the total bank reset switch SW-TR, the product bank reset switch SW-PR, and the column reduction switch SW-C.

The functions of the switches, the special keys, the key contacts, and the key solenoids will be explained hereinafter in detail in connection with the circuit.

The calculator unit

Drive.—Referring to Figs. 1 and 5, the motor M-C rotates a shaft 32 to which is fixed a toothed driving clutch disk 33 adapted to be engaged by a clutch dog 34 carried by a clutch arm 35 fixed to the calculator cycle shaft 36. The clutch dog and arm are normally latched by a lever 37 and associated rebound latch 37'. The latch lever is provided with an armature portion 38 associated with a clutch magnet 40. Energization of the clutch magnet releases lever 37 from the clutch dog and arm, causing the clutch dog to engage in a notch of the driving disk 33 and thus couple shaft 36 to shaft 32 for at least one revolution.

Accumulator banks.—The calculator unit has two accumulator banks ACC-P and ACC-T, re-

spectively the Product and Total banks. The general construction of these accumulator banks is similar to that disclosed in Patent No. 1,976,617. Briefly, shaft 36, through gears 41 (see Fig. 3) rotates a shaft 42 acting, through gears 43, to rotate a shaft 44. The latter shaft, through individual clutch connections selectively rendered effective by double coil entry magnets CM, one for each order, drives gears 45, each meshed with a gear 46 on an indicator wheel 47, rotatably mounted on a shaft 48. Gear 45 is meshed also with a gear 49 of the rotor 50 associated with the same denominational order or column of the readout commutator PRO (see Fig. 12b) of the product bank as the indicator wheel. This product bank commutator is similar to the readout commutator of Patent No. 1,976,617. The gear ratio between shaft 44 and the rotor 50 is such as to cause the rotor to make one revolution for two of the indicator wheel. The rotor 50 of each column has two diametrically opposite brushes 51, alternating during successive cycles, in engaging the collector ring 52 of the column and the segments 53-6 to 8 common to two adjacent columns.

The product bank is used to obtain the product of two factors, which, for the illustrative bill (Fig. 13), are the numbers under the headings "Quantity" and "Price." In the present instance, the quantity factor is limited to three digits and the price factor to five digits, and, therefore, the product cannot exceed eight digits. Accordingly, the product bank has eight columns for the product. The multiplication is effected by the over and over addition method, and a ninth column of the product bank receives the denominational order values of the multiplier, one order at a time, while a tenth column coacts with the ninth column to determine the number of cycles of entry of the multiplicand in the first eight columns.

A total bank ACC-T is used to obtain a balance of the items on one or more bills. The items may be either debit or credit items. The debit item may be considered as the plus item, while the credit item may be considered as the minus item. The debit amounts are entered additively or as plus numbers into the total bank, while the credit amounts are entered, subtractively, as complements. The maximum total to be taken care of by the total bank is not to exceed eight digits and, therefore, eight columns of the bank are provided for this total. A ninth column of the total bank is provided to receive a "9" whenever a complement is entered in the total bank. If the sum of the plus items exceeds 45 or is equal to the sum of the minus items, the ninth column will stand at "0," whereas if the sum of the minus items or complements exceeds the sum of the plus items, the ninth column will read "9." The ninth column is tested for the presence of a "9" to determine whether a complement or credit total is standing in the first eight columns of the total bank. If a credit total is detected, then its complement is read out and the credit typed as a true number. The readout commutator TRO (Fig. 12b) of the total bank is similar in principle to those disclosed in Patents Nos. 2,007,375, and 2,045,437. One order of this commutator is shown diagrammatically in Fig. 3a and comprises axially spaced + and - collector rings respectively wiped by + and - brushes carried by rotors, insulated from each other but which are commonly operated by one gear 48 in step with the operation of the indicator wheel 47 of the same order. There are two diametrically opposite - brushes and two simi-

larly disposed + brushes, and while one + brush is wiping the + collector ring, the opposite + brush is traversing the commutator segments 0 to 9. The — brushes are one step behind the + brushes, so that with the + brush on the "0" segment, one — brush is on the "9" segment and the opposite — brush on the — collector ring. Similarly, with the + brush on the 1, 2, 3 . . . or 9 segment, the — brush is on the 0, 1, 2 . . . or 8 segment.

In entering the complement of a credit item into the total bank, the elusive "1" must be added to the units order. The elusive "1" means is such as disclosed in Patent No. 1,976,617. Referring to Fig. 4, the elusive "1" magnet ELM, upon energization, releases armature latch 55 from the rockably mounted arm 56 which supports the carry over pawl 57 (also see Fig. 3) engaged with the carry cam 58 of the units order wheel 41. The release of arm 56 permits a spring 59 to rock the arm rearwardly against the carry bail 60. After the digit entry portion of an accumulator cycle (see Fig. 11a), a cam 61 (Fig. 4) on shaft 42 acts, through a lever 62 linked to bail 60, to rock the bail forwardly, thereby returning the carry arm 56 into latching engagement with the armature latch 55 of the meanwhile deenergized magnet ELM. As the arm 56 is restored, the pawl 57 engages a tooth of cam 58 to move the units order wheel 41 one step, adding the elusive "1" to the units column of the total bank.

The carry over mechanism between adjacent orders of the accumulator banks is such as disclosed in Patent No. 1,976,617 and includes carry cams 58 and pawls 57 for each of different orders, their carriers 56, latches 55, bail 60, link 62, and cam 61. When an indicator wheel, during the entry period, moves from 9 to 0, a high tooth of the associated carry cam 58 rocks the follower pawl 57 to an extent sufficient to cause a laterally extending ear 57' thereof to rock the latch 57 of the next higher order downwardly so as to release the arm 56 of the latter order. The operation of bail 60, after the entry period, rocks the released arm 56 to cause the pawl 57 carried thereby to advance the latter order one step.

Referring to Figs. 1 and 8, the reset means for the accumulator banks is of the type disclosed in Patent No. 2,049,690. There is a reset magnet RM for each bank, energization of which causes rotation of the shaft 48 of the indicator wheels of the related bank to effect resetting of the indicator wheels and the other, connected elements of the bank. The means for effecting rotation of the shaft 48 comprises a gear 83 fixed to one end of the shaft and meshed with a gear 84 freely mounted on a shaft 85. Rigid with gear 84 is a clutch collar 86 having a single notch 86' adapted to receive the nose of a clutch dog 87 carried by an arm 88 fixed to shaft 85. During rotation of shaft 85, the tail of the clutch dog engages the roller 89 provided on one end of a lever 10 which is normally latched up by armature 71 of the reset magnet RM. During each revolution of shaft 85, the engagement of the tail of the clutch dog with roller 89 cams the nose of the dog outwardly as it traverses the notch 86' of the stationary clutch collar 86. When the magnet RM is energized, lever 10 is unlatched and moves clockwise (Fig. 8) so that roller 89 is no longer in the path of the tail of clutch dog 87. As a result, when the nose of the clutch dog next reaches notch 86', it is free to move into the notch and, in so doing, it couples the gear 84 to the shaft 85 for a single revolution. Gear 84, 75

during its revolution, acts through gear 83 to rotate shaft 48 to reset the bank associated with the energized reset magnet.

Rigid with driven gear 84 is a cam 71' (Fig. 1) which, during the revolution of this gear, cams a bail 72 (also see Fig. 8) counterclockwise, causing an insulating lug 72' thereof to depress the lower spring blade 73 carrying one of the points of the normally closed contacts RMa. Thus, during reset of a bank, the associated contacts RMa are momentarily opened.

The reset magnet of the total bank may be characterized as RM-T, and that of the product bank as RM-P. It should also be noted that similar elements of both banks may be distinguished by appending the letter P to the common reference character to designate association with the product bank and by the letter T to designate association with the total bank. Further, denominational orders of similar elements may be distinguished by appending to the common reference character, the letter u to designate the units order, the letter t to designate the tens order, the letter h to designate the hundreds order, the letters th to designate the thousands order, the symbol 10thd to designate the tens of thousands order, and so on. Further, in the description of relays, the relay contacts may be characterized by the reference number or character of the relay magnet followed by a letter a, b, c, etc.

Cam contacts, impulse emitters, make and break contacts.—Referring to Figs. 1 and 6, the accumulator cycle shaft 36 extends past the total bank ACC-T, and near its right-hand end carries two make and break contact cams 74 for operating make and break contacts 75. Shaft 36 drives, in one-to-one ratio, gears 76 carrying the brushes 77 (see Fig. 12d) of two impulse emitters E+ and E-, respectively, the plus or debit and the minus or credit emitters. Shaft 36 also drives, in one-to-one ratio, through gearing 78 (also see Fig. 7), the shaft 65, previously referred to in the description of the reset means. Shaft 65 carries a plurality of cams A' for operating the several A cam contacts (see Fig. 11a). The make and break contacts 78, the emitters E+ and E-, and the A cam contacts all operate on a "16" point cycle basis, and this "16" point cycle may be referred to as an accumulator cycle (Fig. 11a).

Geared one-to-three to shaft 36 is a shaft 79 which drives, in one-to-one ratio, the brushes 80 (see Figs. 1, 6 and 12b) of auto type emitters E-T and E-P. Driven one-to-one by shaft 79 is a shaft 81 on which are two make and break cams 82 for operating the make and break contacts 83. The shafts 79 and 81 carry the cams R' for operating the R cam contacts. The latter cam contacts, emitters E-P and E-T, and make and break contacts 83 all operate on a "14" point cycle basis, and this cycle may be referred to as the readout cycle (Fig. 11b). As indicated by Figs. 11a and 11b, each readout cycle is coextensive with a series of three accumulator cycles. The readout cycle thus takes three times as long as an accumulator cycle, and the speed of the readout cycle means is such as to suit the requirements for accurate operation of the typewriter mechanism.

As will be brought out further in connection with the description of the circuit, the points of the readout cycle marked "1," "2" . . . "8" correspond to columns of the accumulator banks and designate the points of the readout cycle at which

corresponding columns of the banks are read out. The points "9" to "1" of the accumulator cycle represent the points at which energization of a control magnet CM causes entry of values "9" to "1" into the associated order of the accumulator bank, and the cycle interval "9" to "1" may be referred to as the entry portion of the cycle.

Selector switches.—Also included in the calculator unit are three selector switches SW-#1, SW-#2, and SW-#3. The switch SW-#1 is used during the setting up of values under control of the typewriter keys, the switch SW-#2 is used during the multiplying operation, and the switch SW-#3 is used to correlate controlling operations of the calculator unit to the tab spacing operation of the typewriter. The construction of each selector switch is similar and shown in Fig. 2. The selector switch comprises a common contact segment 84 and contact segments 85 wiped by a brush 86 fixed to a shaft 87. On this shaft is fast a ratchet wheel 88 engaged by a holding pawl 89 which prevents the shaft from being restored, in a counterclockwise direction, by a spring 90, to the home position, which is one step behind the "1" segment. While the brush is in home position, an insulating roller 91 on its rear end holds a pair of contacts SWa and SWb open. As soon as the brush departs from home position, these contacts close. The holding pawl 89 of the switch is released from the ratchet 88, to permit restoration of the brush, upon energization of a release magnet SWR. The ratchet 88 is also engaged by an actuating pawl 92 carried by the armature lever 93 of the stepping magnet SWM. Each time magnet SWM is energized, it causes pawl 92 to advance the brush 86 one step. The construction of the ratchet 88 is such as to prevent its advance and advance of the brush 86 from segment 85-10 or from its "10" position should an impulse be received by the stepping magnet SWM while the brush is in the "10" position.

Circuits and operation

The machine is connected to a current service line through a common plug 100 (left of Fig. 12a). Binding posts *b* are provided in the calculator unit, as indicated in Fig. 12a, and the connections to and from the binding posts may be referred to as connections *b*-1, *b*-2, *b*-3, etc. The connections leading upwardly in Fig. 12a from the binding posts connect the calculator unit to the typewriter and are gathered in the cable 8, as shown in Fig. 1.

To run the typewriter unit by itself, the typewriter switch SW-T is closed, forming the following circuit (Fig. 12a):

Typewriter motor circuits #1.—From one side of the plug 100, through connection *b*-1, switch SW-T, typewriter motor M-T, connection *b*-2, to the opposite side of the plug.

When it is desired to operate the typewriter jointly with the calculator, the three pole switch SW-L is closed, establishing the following circuits (Fig. 12a):

Typewriter motor circuit #2.—From one side of plug 100, through connection *b*-1, the left pole of switch SW-L, motor M-T, connection *b*-2, to the opposite side of the plug.

Calculator motor circuit.—From one side of plug 100, through connection *b*-1, the center pole of switch SW-L, connection *b*-4, common line 101, calculator unit motor M-C, opposite common line 102, connection *b*-3, the right pole of switch SW-L, connection *b*-2, to the other side of the plug.

As long as the switch SW-L is closed, current is fed to opposite common lines 101-102 and the calculator motor M-C and the typewriter motor M-T remain in operation.

Relating to switch SW-#3

Fig. 12f shows the circuit connections through switch SW-#3 (see Fig. 2 for mechanical construction) which is used to correlate the tabular spacing operations and, hence the vertical fields of the bill, with the calculator operations. To each of the ten segments of switch SW-#3 is connected a plug socket 103 which may be wired by a plug connection 104 to any of the five plug sockets 105. Each segment of the switch, as well as the connected plug socket 103, corresponds to one of the fields of the bill, as indicated in Fig. 12f. For the present case, the lot number field socket is left unconnected from any of sockets 105. For the typing of the illustrative bill (Fig. 13), the quantity field socket 103-2 is connected to socket 105-2, the dollars amount socket 103-6 is connected to socket 105-3, the dollars credit amount socket 103-8 is connected to socket 105-4, and the total socket 103-10 is connected to socket 105-5.

The sockets 103 are successively connected to common line 101 by stepping the brush 86 of the selector switch along segments 85 in accordance with the tabular spacing of the bill and, therefore, in accordance with the fields of the bill brought to typing position. In order that the selection of sockets 103 by switch SW-#3 be repeated for each line of the bill, the brush of this switch is restored to home position as an incident to each carriage return operation. When the carriage return key CR is operated, key contacts 28-CR close, forming the following circuit (Fig. 12a):

Switch-#3 release magnet.—Common line 102, through release magnet SWR-3, connection *b*-36, key contacts 28-CR, connection *b*-31, common line 101.

When the carriage reaches the beginning-of-the-line position, contacts 24 (see Fig. 10) close, as explained before. These contacts are in parallel with the key contacts 28-CR, and closure thereof forms a parallel circuit through the release magnet. Thus, even if the carriage return operation were effected manually instead of as a result of depression of the carriage return key, the closure of contacts 24 would result in energization of magnet SWR-3. Energization of this magnet causes the return of the brush 86 to home position, one step behind the "1" segment of the switch SW-#3.

The first operation on the bill sheet is to type in the heading. Since the description field, along a vertical extension of which the heading lies, corresponds to socket 103-5, which is not connected to any of sockets 105, the typing in the heading will not affect the operation of the calculator unit. After typing the heading, the operator manually initiates a carriage return operation and spaces the bill sheet to position the first item line of the bill at the typing line. As a result of the carriage return operation, the brush of switch SW-#3 is restored to home position. The tab key is then depressed to tabulate the carriage to the first column of the lot number field. The depression of the tab key closes key contacts 28-Tab to form the following circuit (Fig. 12a) through the stepping magnet SWM-3 of switch SW-#3:

Switch SW-#3 stepping magnet.—Line 102,

15

through magnet SWM-3, connection **b-38**, key contacts **28-Tab**, connection **b-31**, line **101**.

Energization of magnet SWM-3 steps the brush **86** to segment "1" of switch SW-#3, connecting the socket **103-1** to common line **101** (see Fig. 12f). As socket **103-1**, corresponding to the code number field, is not connected to any of sockets **105**, the calculator unit will not be conditioned for correlation with the code number field. The operator now proceeds to type the code number. Having finished typing the code number, the tab key is depressed to bring the first column of the quantity field to typing position. This tabular spacing operation again forms the circuit of magnet SWM-3, causing the feeler of switch SW-#3 to move to segment "2." When this occurs, the following circuit is established (Fig. 12f):

Coil 110 circuit.—Line **101**, through position "2" of switch SW-#3, socket **103-2**, connection **104** to **20** socket **105-2**, coil **110**, line **102**.

Energization of coil **110** closes contacts **110a** to form the following circuit (lower part of Fig. 12e):

Coil 111 circuit #1.—Line **101**, contacts **110a**, coil **111**, line **102**.

Coil **111** closes contacts **111a** (Fig. 12a). Closure of these contacts is a condition precedent to the completion of circuits, traced later, for entering values typed into the quantity, price, amount, and credit fields of the bill (Fig. 13) into value retaining means provided in the calculator unit. Thus, energization of coil **111** conditions the calculator unit to receive values typed on the bill.

The value retaining means

The value retaining means comprises a bank of relays including eight columns of value retaining coils **114** (Fig. 12c) and associated relay contacts **114a** and **b**. For convenience, the bank of **114b** contacts is shown separately in Fig. 12d. The denominational order of each column of the value retaining bank is indicated at the bottom of the column (Figs. 12c and 12d). During the typing of the quantity, the hundreds, tens, and units orders of quantity digits are entered, respectively, into the first or left-hand column of the value retaining bank, the second, and third columns. During typing of the price factor, the successive orders of price digits are entered into the fourth, fifth, sixth, seventh, and eighth or right-hand column of the value retaining bank. During typing in the amount or credit section of the bill, the eight columns of the value retainer bank correspond to the eight columns of the amount or the credit section, and are successively set up, from left to right, in the same order as the digits are typed in the corresponding columns of the amount or credit section. Each column of the value retainer bank includes ten value coils **114** and related **114a** and **b** contacts, corresponding to digits 0 to 9, as indicated for the left hand column in Figs. 12c and **d**.

In effect, the value retaining bank is equivalent to a counter bank which does not require cyclical operation and differential timing to receive values. Thus, the values typed into the quantity, price, amount, and credit sections may be entered into the value retaining means without requiring a counter cycle for each digit entry. This saves considerable time in the operation of the machine. If a cyclical counter were used, it would be necessary to initiate a counter cycle as a timed incident to the typing of each digit to be entered, and it would be necessary to wait for one cycle to be completed before the next digit

5

could be typed and entered. The value retaining means, as will be made clear further on, receives a digit entry as an immediate consequence of the typing of the digit, just as though the value retaining means were an impressionable medium similar to the sheet on which the digit is being typed.

Relating to entry into the value retaining bank

The entry means includes a pair of relay coils **115** (upper right of Fig. 12a) for each digit key. The energization of the pair of coils **115**, corresponding to a digit, closes a row of eight **115a** contacts (Fig. 12c) which are in series with the eight value coils **114** of the corresponding digit row of the value retaining bank. The closure of the **115a** contacts partially closes the circuits of the related value coils, but only one of these circuits at a time may be completed, depending on the operation of the selector switch SW-#1. This switch functions to correlate the columns of the retaining relay coils successively with the corresponding columns of the bill into which the digits to be entered are being typed. In effect, the switch SW-#1 successively places the columns of the value retaining bank under control of the digit keys just as the intraline spacing of the corresponding columns of the bill successively places them in condition to be typed under control of the digit keys.

Concerning switch SW-#1.—Initially, the brush **86** of switch SW-#1 is in home position, one step behind the "1" segment **85** (see Fig. 2). When a digit key is operated to type the digit in the first column of the quantity, amount, or credit section of the bill, the stepping magnet SWM-1 of switch SW-#1 is energized to step the brush **86** to the "1" segment which is in the circuit of the first or left hand column of coils **114** (see Fig. 12c). The switch reaches this position immediately before the operation of the key results in the energization of the related key coils **115** and the consequent closure of the row of contacts **115a**. As a result of the positioning of switch SW-1 and closure of **115a** contacts, an initiating or main circuit is formed through a coil **114** in the left hand column of the retaining relay bank. The switch SW-1 selects the column of the value bank of which a coil **114** is to be energized, while the contacts **115a** select, in this column, the particular coil corresponding to the digit which is being typed by the active digit key. The energized coil **114** closes its **114a** contacts to form a stick circuit, operative after opening of the momentarily closed **115a** contacts.

When the second digit is typed, the switch SW-#1 is stepped to position "2" to select the second column of the value retainer bank, and so on for the third, fourth, and to the eighth column of the retainer relay bank. If, instead of operating a digit key, the space bar SP is operated, the switch SW-1 will be similarly stepped along, thereby maintaining the columns of the retaining relay bank coordinated with the intraline spacing of the corresponding orders of the bill, columns in which the value to be entered is being typed.

Entry of quantity and price factors.—To simplify the explanation, assume that the quantity or multiplier factor is 123 and the price or multiplicand factor is 45678. It will be recalled that the bill has been tabulated to the first quantity column and that coil **111** is energized to close contacts **111a** (Fig. 12a). When key **10-1** is now operated to type the digit 1 into the hundreds or

70

75

first column of the quantity field, the inner and outer key contacts 28 and 28' (see Fig. 9) are closed in succession. Contacts 28 are closed first by the action of roller 26 and, after closure of contacts 28, the left hand blade of the latter contacts is moved further to cause contacts 28' to close. The closure of contacts 28 thus precedes the closure of contacts 28'. Referring now to Fig. 12a, the closure of contacts 28 of key 10-1, with contacts 111a in closed condition, establishes the following circuit:

Coil 120 circuit.—Line 101, normally closed contacts 111a, contacts 111a, connection b-6, common 118 of the key contacts, inner key contacts 28-1, common 119 of the key contacts, connection b-5, coil 120, line 102.

Coil 120 closes contacts 120a to form the following circuit (Fig. 12a):

Switch SW-#1 stepping circuit.—Line 101, contacts 120a, in parallel through magnet SWM-1 and a coil 121, line 102.

Energization of magnet SWM-1 steps the feeler of switch SW-1 to the "1" column segment 85, preparing the first or left hand column of the coils 114 for receiving the first quantity digit. The selection of a coil in this column is controlled by closure of outer key contacts 28' which occurs immediately after closure of contacts 28. Thus, it is made certain that the selection of the column of coils 114 by switch SW-1 to receive an entry takes place before the selection of a coil 114 in the selected column. It should be noted that even were contacts 28 and 28' to be closed simultaneously, the column selecting action of switch SW-#1 would precede the digit coil selecting action of the key contacts because of the stepping action of the switch being effected rapidly and being completed before the key coils 115 succeed in closing the 115a contacts.

As a result of the closing of key contacts 28'-1, the following circuit forms (Fig. 12a):

Key coil circuit.—Line 101, contacts 117a, 111a, connection b-6, common wire 118, contacts 28'-1, connection b-23, key coils 115-1, common wire 122, line 102.

Referring to Fig. 12c, coils 115-1 close the row of eight contacts 115a-1, but with switch SW-#1 now in first column selecting position, the closure of contacts 115a-1 only in this first column is effective to form a main circuit through the coil 114-1 of this column, as follows (Fig. 12c):

Value coil main circuit.—Line 102, coil 114-1 of the first column, contacts 115a-1 in series therewith, common wire 123, the connected, normally closed space relay contacts 124a, contacts 125a, column reduction relay contacts 126a, position "1" of switch SW-#1, line 101.

A stick circuit for the energized coil 114-1 of the left hand column is formed by closure of contacts 114a-1, as follows (Fig. 12c):

Value coil stick circuit.—Line 102, coil 114-1, contacts 114a-1, common wire 127, coil 125, in parallel through cam contacts A3 and column shift relay contacts 128a-h, common wire 129, in parallel through cam contacts A10 and total entry relay contacts 130a, normally closed contacts 131a, 132a, connection b-33 (continue with Fig. 12a), the left, normally closed side of error key contacts EKa, connection b-34, line 101.

Coil 125, energized by the above circuit, opens contacts 125a, common to the main circuits of the left hand column of coils 114, to make certain that not more than one coil 114 will be energized in this column.

The successive typing of the remaining digits of

the quantity and price sections of the bill repeatedly closes the SWM-1 circuit to step the switch SW-#1 to the successive switch positions correlated with the different value retaining relay columns. The main circuit of a coil 114 in the second column differs from the previously traced main circuit of the first column in extending through contacts 133a and position "2" of switch SW-#1. The stick circuit of the second column is similar to the stick circuit traced above but extends through a coil 133 and in parallel through cam contacts A2 and column shift contacts 128a-t. The coil 133 opens contacts 133a to prevent energization of more than one coil 114 in the second column. The main circuit of the units quantity column extends through contacts 134a and position "3" of switch SW-#1, while its stick circuits extends through coil 134, functioning to the same effect as coil 125 in preventing energization of more than one relay coil in the same column, and through cam contacts A1 and parallel column shift contacts 128a-u. The main circuits of coils 114 of the fourth to eighth columns, inclusive, of the retaining relay bank are established by the typing of the price digits and respectively include contacts 135a, 136a, 137a, 138a, and RH_a, and positions "4," "5," "6," "7," and "8" of the switch SW-1. The last three columns do not include column reduction contacts 126a. All of the last five columns do not include any A cam contacts and column shift contacts as these are unnecessary for the price columns, the price being entered into the product bank during one accumulator cycle, as will be explained later. The stick circuits of the fourth to seventh columns coils 114 also include coils 135, 136, 137, and 138, functioning to the same effect as coil 125 of the first column stick circuit in opening the main circuits to prevent more than one coil in a column being energized during the typing of the item. The stick circuit of the right hand or eighth column of coils 114 includes a multi-contact relay magnet RH and a relay coil 139, energization of both of which determines that the last digit of the price or multiplicand factor has been set up and that multiplication may begin. Magnet RH opens contacts RH_a in the main circuit of the last column to prevent energization of more than one value retaining coil in this column. Energization of the coils 114 closes associated 114b contacts (see Fig. 12d). In the assumed example, the contacts 114b-1, 2, 3, 4, 5, 6, 7, and 8 of the first to eight columns are now closed, representing the quantity factor 123 and the price factor 45678. The closed 114b contacts control entry of these factors into the product bank ACC-P to be multiplied, in a manner which will be explained hereinafter.

The control by the space bar.—It is not desired to type a "0" in any of the dollars order columns of the bill, unless preceded by a significant digit, but to leave such columns blank and to space to the next column. This is done by operation of space bar SP of the typewriter. The operation of the space bar causes switch SW-#1 to step along so as to maintain the switch positions in proper correlation to the columns of value coils 114 and the corresponding bill columns. The operation of the space bar also causes the contacts 124a in the main circuits of each column of coils 114 to open in order to make certain that a coil 114 of any column corresponding to a bill column being left blank is not picked up or energized.

When the space bar SP is operated, its associ-

ated contacts 28-SP close, completing the following circuit (Fig. 12a):

Coil 140 circuit.—Line 101, contacts 117a, 117a, connection b-8, contacts 28-SP, connection b-7, coil 140, line 102.

Coil 140 closes contacts 140a to form a circuit through multiconta^t space magnet 124, as follows (Fig. 12a):

Magnet 124 circuit.—Line 101, contacts 140a, magnet 124, line 102.

To maintain magnet 124 energized after contacts 140a open, the magnet closes contacts 124b to form the following circuit (Fig. 12a):

Magnet 124 stick circuit.—Line 101, in parallel through normally closed contacts 120b and 121a, contacts 124b, magnet 124, line 102.

Magnet 124 opens contacts 124a (Fig. 12c) of the main circuit lines of the columns of the value retainer relay bank to prevent energization of any of coils 114 during the spacing operation.

Energization of coil 140 by the coil 140 circuit also closes contacts 140b (Fig. 12a), which shunt contacts 120a of the switch SW-#1 stepping circuit, to cause energization of magnet SWM-1, as a result of which switch SW-#1 is stepped to the next position, just as when a digit key is operated. When magnet SWM-1 is energized, the coil 121, in parallel therewith, also is energized and opens contacts 121a in the magnet 124 stick circuit, but the parallel contacts 120b continue to hold this stick circuit closed until a digit key is operated for setting up the first significant digit. When a digit key is operated, the coil 120 circuit forms, and coil 120 closes contacts 120a to establish the magnet SWM-1 circuit for advancing the switch SW-#1 and also opens contacts 120b of the magnet 124 stick circuit. When the magnet SWM-1 circuit forms, parallel coil 121 is also energized, opening contacts 121a to cause a complete break in the stick circuit of magnet 124. Thus, contacts 121a time the deenergization of the space relay magnet 124 to prevent reclosing of contacts 124a of the main circuit lines of the value coils 114 (Fig. 12c) until the switch SW-1 has been stepped to the position for selecting the value retaining column corresponding to the bill column in which the first digit is being typed.

Maintained action of coil 111 during typing of price.—When the third or units order quantity column is typed, a coil 114 in the corresponding third column from the left of the value retaining bank is energized and held by its stick circuit. Common to the stick circuits of the column is the coil 134 (Fig. 12c) which, in addition to opening contacts 134a in the main circuit to prevent more than one coil 114 of the column being picked up, also closes contacts 134b in series with contacts 111b of coil 111 (see Fig. 12e). At this time, switch SW-#3 is still in quantity field position "2" (Fig. 12f), so that coil 110 is energized to hold contacts 110a closed, with the result that the coil 111 circuit #1 is still in effect, and coil 111 is now holding contacts 111b closed. Now, when contacts 134b close, the following circuit forms (Fig. 12e):

Coil 111 circuit #2.—Line 102, coil 111, contacts 111b, 134b, 142a, 143a, RHb, line 101.

After the units order quantity digit is typed, the operator actuates the tab key to tabulate the first column of the price section of the bill to typing position. The operation of the tab key forms the switch SW-#3 stepping magnet circuit, bringing the switch SW-#3 to position "3" (Fig. 12f) which is not connected to any of sockets 105. When the switch left position "2," coil 110 was

deenergized and contacts 110a opened to break the coil 111 circuit #1. The energization of coil 111 is maintained, however, through the coil 111 circuit #2 formed as a result of the previous entry of the units order quantity digit. Consequently, contacts 111a remain closed during the typing in the price columns of the bill, so as to enable the last five columns of the value retaining bank to be set up in accordance with the price factor.

As a result of the typing of the cents units order or right hand digit of the price, the stick circuit of a corresponding digit value coil 111 in the right hand column of the value retaining bank is established. As stated before, this stick circuit includes coil 139 and the multi-contact relay magnet RH (see Fig. 12c).

Magnet RH opens contacts RHb in the coil 111 circuit #2, and coil 111 is now deenergized. When the operator, after typing the right hand price digit, tabulates the description field to typing position, the switch SW-3 is stepped to position "3" (see Fig. 12f), the connected socket 103-3 of which is not plugged to any of sockets 105. Now, with coil 111 deenergized and contacts 111a open, the typing of any digits in the description field will not cause entry of the digits into the calculator unit.

Restoration of switch SW-#1.—The entry of the units order digit into the right hand column of the value retaining bank causes energization of magnet RH and coil 139. As explained above, magnet RH opens contacts RHb to break the second circuit of coil 111, resulting in deenergization of the coil and opening of contacts 111a. The magnet RH also closes the right side of contacts RHc (bottom of Fig. 12b) to cause the switch SW-#1 to be restored to initial condition. This switch, having performed the function of correlating the columns of the value retaining bank to the corresponding columns of the quantity and price sections, may be restored to home position after the right hand price digit has been entered. As will be explained hereinafter, the product of the quantity and price is typed automatically into either the amount or credit sections of the bill, and this typing is required to enter the product into the value retaining bank. The restoration of the switch SW-#1 to home position prepares the switch for correlating the columns of the value retaining bank to the columns of the amount or credit section during the typing of the product in either one of these sections. The restoration of the switch SW-#1 occurs as a result of energization of magnet RH, which closes the right side of contacts RHc to establish the following circuit (Fig. 12b):

Switch SW-#1 release magnet.—Line 111, the right side of contacts RHc, selector switch contacts SWa-1 (closed as soon as the brush leaves home position), magnet SWR-1, line 102.

Energization of magnet SWR-1 restores the brush of switch SW-#1 to home position.

Multiplication

65 Magnet RH, energized as a result of entry of the units order price digit, initiates multiplying operation by the product bank, the quantity entry being treated as the multiplier and the price entry as the multiplicand. The multiplying operation is by the over and over addition method and requires the performance of accumulator cycles by the product bank; hence, the clutch magnet 40 (Figs. 1 and 5) must first be energized. When magnet RH was energized, it closed contacts RHd, forming the following circuit (Fig. 12f):

Clutch circuit #1.—Line 102, clutch magnet 40, wire 145, contacts RH_d, line 101.

Energization of clutch magnet 40 initiates rotation of calculator shaft 36 (Figs. 1, 6, and 7) to perform accumulator and readout cycles (Figs. 11a and 11b). As previously explained, a series of three successive accumulator cycles accompanies each readout cycle. Hereinafter, the time of operation of R cam contacts may not only be referred to the portion of the readout cycle when the operation occurs but also to the accumulator cycle which accompanies this portion of the readout cycle. Similarly, the time of operation of A cam contacts may be referred to the accompanying portion of the readout cycle.

During the first accumulator cycle, cam contacts R9 (Fig. 11b) close, and when A9 cam contacts (Fig. 11a) also close at the "15" point, the following clutch circuit forms (Fig. 12f):

Clutch shunt circuit.—Line 102, magnet 40, contacts R9, contacts A9, line 101.

Cam contacts R9 remain closed during the second accumulator cycle, so that the clutch shunt circuit repeats, maintaining the clutch engaged for the third cycle, independently of clutch circuit #1. During the third accumulator cycle, the contacts R9 are open when cam contacts A9 close at the "15" point, and the continuation of the clutch engagement for the next accumulator cycle then depends on clutch circuit #1, requiring contacts RH_d to be closed. Assuming the multiplication is completed during the third cycle, the magnet RH is deenergized when cam contacts A5 make, as will be brought out later and, therefore, contacts RH_d open and the clutch is disengaged at the D point of the third accumulator cycle. If multiplication is not completed during the third accumulator cycle of the first series, then clutch circuit #1 continues in effect and a fourth accumulator cycle or the first of a second series starts. During the latter cycle, cam contacts R9 make again and the clutch shunt circuit takes effect to cause the second and third accumulator cycles of the second series to be performed. Thus, if multiplication is not completed during a series of three accumulator cycles coextensive with a readout cycle, the calculator unit performs a complete new series of accumulator cycles. When multiplication is completed during any series, the clutch shunt circuit continues calculator shaft 36 in operation to the end of the series. Thus, the disengagement of the clutch can occur only at the end of a series of three accumulator cycles or the coextensive readout cycle.

Entry of multiplier into product bank.—The multiplication by the product bank is by the over and over addition method, involving entry of the units, tens, and hundreds orders of the multiplier (quantity) in succession. This successive entry of the orders of the multiplier is controlled by successive energization of column shift magnets 128-u, 128-t, and 128-h (Fig. 12e), of which the respective contacts 128a-u, t, and h are in the stick circuits of the third, second, and first columns of the value retaining coils 114 (Fig. 12c), which have received the quantity factor or multiplier. The energization of magnets 128u, t, and h in succession is controlled by the selector switch SW-#2, the brush of which is advanced one position upon each agreement between the reading of the cycling counter, comprising column 10 (the left hand or highest order) of the product bank, with the reading of column 9 which receives the units, tens, and hundreds multiplier digits in succession. Initially, the columns of the product

bank are at zero and, consequently, the brushes 51 of the ninth and tenth orders, or columns 9 and 10 of the product bank readout commutator PRO, are on common zero segment 53-0, as indicated in Fig. 12e.

It will be recalled that magnet RH and coil 139 were energized as a result of the entry into the right hand column of the value retaining means of the cents units price digit. Magnet 10 RH closed contacts RH_d to establish clutch magnet circuit #1, traced above, to initiate accumulator cycles. Magnet RH also closed contacts RHe, and when cam contacts A5 close at the "14" point of the first accumulator cycle (see 15 Fig. 11a), the following circuit forms (Fig. 12e):

Switch SW-#2 stepping circuit.—Line 102, stepping magnet SWM-2, collector ring 52 of column 10 of the product readout commutator PRO, the column 10 brush 51, segment 53-0, brush 51 of the ninth column, column 9 collector ring 52, contacts RHe, normally closed relay contacts 148a, 149a, 150a, cam contacts A5, line 101.

Magnet SWM-2 now advances the feeler of switch SW-#2 from home position to position "1." When this happens, the following circuit forms (Fig. 12e):

Magnet 128-u circuit.—Line 102, magnet 128-u, a relay coil 151-u, contacts 152a-u, contacts 134b (closed by energized coil 134 of the stick circuit of the third or units quantity order column of the value retaining bank), the "1" position of switch SW-2, contacts 153a, line 101.

Coil 151-u closes stick contacts 151a-u to form a holding circuit for magnet 128-u and coil 151-u, maintained until the switch SW-#2 is advanced to position "2."

Magnet 128-u stick circuit.—Line 102, magnet 128-u, coil 151-u, contacts 151a-u, the "1" position of switch SW-#2, contacts 153a, line 101.

40 Magnet 128-u opens contacts 128a-u in the stick circuit of the energized value coil 114 of the units order quantity column of the value retaining bank, but this stick circuit remains closed through cam contacts A1, in parallel with contacts 128a-u, until after the entry period "9" through "1" of the second accumulator cycle.

Thus, during the first accumulator cycle, initiated by closure of contacts RH_d to form clutch magnet circuit #1, magnet 128-u and coil 151-u have been energized. The energization of magnet 128-u and coil 151-u was timed by closure of cam contacts A5 to occur at the "14" point of the first accumulator cycle. Magnet 128-u closes the group of five contacts 128b-u (Fig. 12d) each connected to one of the entry magnets CM of columns 1 to 5 (units to tens of thousands orders) of the product bank, thereby preparing these columns to receive the five digits of the multiplicand. Magnet 128-u also closes contacts 128c-u connected to magnet CM of column 9 of the product bank, preparing this column to receive the units order digit of the multiplier. Coil 151-u closes contacts 151b-u connected to magnet CM of column 10 of the product bank, preparing this column to receive a cycle counting impulse. The above operations all take place during the first accumulator cycle following the closure of cam contacts A5 at "14." The entry of debit values into the product bank is timed by the plus emitter E+ (Figs. 1 and 12d), the brush 11 of which is now on an insulating segment of the emitter ring. Thus, entry of the values into the product bank does not occur during the first accumulator cycle, but is deferred until the second accumulator cycle.

In series with the brush of the plus emitter E+ is a pair of contacts 154a, closed except when a credit entry is being made. Contacts 154a are closed by energization of coil 154 which occurs as soon as switch SW-L (Fig. 12a) is closed to place current on the opposite lines 101 and 102. The circuit for coil 154 follows (Fig. 12f):

Coil 154 circuit.—Line 102, coil 154, credit relay contacts 155a, line 101.

Coil 154 remains energized to hold contacts 154a closed except when a credit entry is being made, during which time contacts 155a open, as will be brought out further on.

Entry of factors.—The multiplier and multiplicand are now represented by the closed 114b contacts (Fig. 12d) of the value retainer bank. Since the positions of the contacts 114b along their columns correspond to different values, the representation thereby of values may be considered as a positional value setting or representation. This positional representation is converted by the emitters E+ or E- into differentially timed equivalents for entry into the columns of the product bank. During the second accumulator cycle, which may be considered as the first multiplying cycle, the units order value of the multiplier is entered into column 9 of the product bank, the multiplicand is entered into columns 1 to 5, and column 10 is advanced one unit step as an indication of the performance of one multiplying cycle.

In the assumed example of a multiplier of 123, the units order value is "3" and contacts 114b-3 of the third column from the left of the bank of 114b contacts are closed. When the brush of emitter E+ reaches position "3" during the first multiplying cycle, the following circuit is established (Fig. 12d):

Multiplier entry circuit.—Line 101, make and break contacts 75 (see the time chart, Fig. 11a), contacts 154a (now closed), the brush 71 of emitter E+, the "3" segment of the emitter, common wire 156 of the row of 114b-3 contacts, the now closed 114b-3 contacts of the third column from the left, the common 157 of the latter column, the right, normally closed, side of a pair of contacts 130b of the total entry multi-contact relay magnet 130, the now closed 128c-u contacts, magnet CM of column 9 of the product bank, the common 158 of magnets CM, line 102.

Energization of this magnet CM at the "3" point of the cycle causes entry of the value "3" into column 9 of the product bank, as a result of which its readout brush 51 is advanced to commutator segment 53-3 (see Fig. 12e).

The entry circuits of the multiplicand are similar to the above entry circuit, except that they are routed through the 128b-u contacts, now closed by energized column shift magnet 128-u, into columns 1 to 5 of the product bank. Thus, by the end of the entry period of the second accumulator cycle, the multiplicand factor is standing in the five lowest order columns, or columns 1 to 5 of the product bank.

At the "1" point of the first multiplying cycle, an entry circuit is formed through magnet CM of column 10 of the product bank to advance the latter column one step as a count of the cycle of multiplication which has taken place. The entry circuit of column 10 is as follows (Fig. 12d):

Cycle counting entry circuit.—Line 101, contacts 75, 154a, position "1" of emitter E+, the common side of the "1" row of 114b contacts, line 158, contacts 151b-u (closed by now-energized

coil 151-u), magnet CM of column 10, common 158, line 102.

The energization of this magnet CM causes the readout brush 51 of column 10 to advance to segment 53-1 (see Fig. 12e).

Thus, at the end of the entry period of the first multiplying cycle, columns 1 to 5 of the product bank contain the multiplicand, column 9 contains the units order digit of the multiplier, and column 10 reads "1."

The units order digit of the multiplier, having been entered into column 9 of the product bank, the set up of the units quantity order or third value retainer column from the left must be cleared. When magnet 128-u was energized at the "14" point of the first accumulator cycle, it opened contacts 128a-u in the stick circuit of the latter column, but the stick circuit was maintained through cam contacts A1 which were then closed and which do not open till the end of the entry period of the first multiplying cycle (Fig. 11a). Upon the opening of cam contacts A1, the stick circuit of the units order multiplier column of coils 114 breaks and the closed 114b contacts of the column open. Thus, after the units order multiplier digit has been entered once in column 9 of the product bank, further entry of this units digit is prevented, and column 9 remains set at the reading of the units order value of the multiplier, which, in the assumed example, is "3."

The number of multiplying cycles performed to multiply the multiplicand by the units order digit of the multiplier depends on the number of cycles which are required to bring cycle counting column 10 of the product bank into agreement with column 9. In the present example, three multiplying cycles occur before column 10 is advanced to "3," which matches the reading "3" in column 9. During each of the three multiplying cycles, the multiplicand is entered into columns 1 to 5 of the product bank, and column 10 is advanced one step. At the end of the entry period of the three multiplying cycles, the multiplicand has been multiplied by "3" (the units order multiplier digit), and column 10 stands at "3."

During the first multiplying cycle, when cam contacts A1 opened, the stick circuit of the units order multiplier column of the value retaining bank was broken, as explained before. As a result, coil 134 was deenergized, causing contacts 134b of the magnet 128-u main circuit to open. The magnet 128-u remains energized, however, through the magnet 128-u stick circuit which does not break until switch SW-#2 leaves position "1."

At the end of the entry period of the third multiplying cycle, the column 10 brush 51 of the commutator PRO is on segment "3" which is also engaged by the brush 51 of column 9. When cam contacts A5 close at "14" of the third multiplying cycle, the switch SW-#2 stepping circuit is again formed, the circuit extending this time through common segment "3" of columns 9 and 10. This circuit advances the switch SW-#2 to position "2." As a result of the switch leaving position "1," the stick circuit of magnet 128-u and coil 151-u (Fig. 12e) is broken, and contacts 128b-u, 128c-u, and 151b-u (Fig. 12d) open.

When switch SW-#2 reaches position "2," the circuit of column shift magnet 128-t is established (Fig. 12e):

Magnet 128-t circuit.—Line 102, magnet 128-t,

coil 151-t, contacts 152a-t, contacts 133b, position "2" of switch SW-#2, contacts 153a, line 101.

Contacts 133b in the above circuit have been closed by energization of coil 133 in the stick circuit of the second value retainer column from the left, which contains the tens order digit of the multiplier.

The closure of contacts 151a-t forms the stick circuit of magnet 128-t and coil 151-t, which remains in effect until switch SW-#2 leaves position "2."

Coil 151-t closes contacts 151b-t (Fig. 12d) which shunt contacts 151b-u and replace the latter in forming the cycle counting entry circuit.

Magnet 128-t opens contacts 128a-t (Fig. 12c) in the stick circuit of the second value coil column from the left. The stick circuit of the energized coil 114-2 in the latter column remains made through cam contacts A2. Magnet 128-t closes contacts 128c-t to connect the tens order multiplier column of contacts 114b (the second from the left, Fig. 12c) to column 9 of the product bank. Magnet 128-t also closes the groups of five 128b-t contacts to connect the five multiplicand columns of contacts 114b to columns 2 to 6 of the product bank, thus shifting the entry circuit of each order of the multiplicand to the next higher order of the product bank, equivalent to multiplying the multiplicand by ten. Thus, as a consequence of switch SW-#2 advancing to position "2," the control of the column 10 of the product bank is shifted to contacts 151b-t (Fig. 12d) the entry circuit of column 9 is shifted, through contacts 128c-t to the tens order multiplier column of contacts 114b, and the entry circuits of the multiplicand are shifted, through the group of contacts 128b-t to columns 2 to 6 of the product bank. All of this occurred as a result of the matching of the readings of columns 9 and 10 of the product bank during the third multiplying cycle, which is the fourth accumulator cycle of the series initiated by completion of the entry of the last multiplicand digit in the right hand column of the value retaining bank. During the next cycle or the fourth multiplying cycle, the cycle counting entry circuit adds "1" to the previous "3" reading of column 10 of the product bank, the multiplier entry circuit adds "2" (the tens order digit of the multiplier), represented by the second column 114b contacts from the left, to the column 9 reading of "3," and the multiplicand is entered in columns 2 to 6 of the product bank. At the end of the entry period of the fourth multiplying cycle, cam contacts A2 (Fig. 11a) open, breaking the stick circuit of the tens order multiplier column of coils 114 (Fig. 12c), causing contacts 114b-2 (Fig. 12d) to open, to prevent more than one cycle of entry of the tens order multiplier digit into column 9 of the product bank. When the stick circuit of the tens order multiplier column of coils 114 is broken, the common coil 133 is deenergized, opening contacts 133b in the main circuit of magnet 128-t. The stick circuit of magnet 128-t and connected coil 151-t maintains these two energized until switch SW-2 leaves position "2."

During the fifth multiplying cycle, the multiplicand is again entered into columns 2 to 6 of the product bank and column 10 is advanced one step, bringing its reading to "5" which matches the reading "5" of column 9. When cam contacts A5 make during this cycle, the switch SW-#2 stepping circuit is again formed, advancing switch SW-#2 to position "3" (Fig. 12e). As a result, magnet 128-t and coil 151-t are deenergized, and

the main circuit of magnet 128-h and coil 151-h made through contacts 152a-h, contacts 125b, and position "3" of switch SW-#2. The closure of contacts 151a-h form the stick circuit of magnet 128-h and coil 151-h, which remains in effect till switch SW-#2 leaves position "3." Coil 151-h closes contacts 151b-h which are in parallel with contacts 151b-u and 151b-t and replace the latter in forming the cycle counting entry circuit. Coil 128-h opens contacts 128a-h in the stick circuit of the left hand or units order multiplier column of value retaining coils 114, leaving the stick circuit made through cam contacts A3. Magnet 128-h also closes contacts 128c-h (Fig. 12d) to connect the left hand column of 114b contacts to column 9 of the product bank. Magnet 128-h also closes the group of five 128b-h contacts to connect the five right hand columns of contacts 114b, set up in accordance with the multiplicand, to columns 3 to 7 of the product bank, thus shifting the entry circuit of each order of the multiplicand to the next higher order of the product bank.

During the next accumulator cycle, which is the sixth multiplier cycle, "1" is added to column 10 of the product bank, "1" (the hundreds order multiplier digit in the assumed example) is added to column 9, and the multiplicand is entered into columns 3 to 7 of the product bank. When cam contacts A3 open during the sixth multiplier cycle, the stick circuit of the left hand column of coils 114 is broken and coil 125 therein is deenergized, breaking the main circuit of magnet 128-h and coil 151-h. During this same cycle, the readings of columns 9 and 10 of the product bank match and when cam contacts A5 close, the circuit of switch SW-#2 is again made and the switch advances to position "4," causing deenergization of magnet 128-h and coil 151-h.

It is to be noted that the multiplication of the two factors is by the over and over addition method, with the multiplicand entry shifted to the next high orders of the product bank for each shift to the next higher order of the multiplier. In the present case, when the hundreds order of the multiplier has multiplied the multiplicand, the multiplication operation is complete and the product bank contains the product of the two factors. Columns 1 to 7 of this bank directly receive the product, and if the product exceeds seven digits, the usual carry-over operations enter the eighth digit into column 8. Since, for the purposes of the disclosure, the number of digits in both factors is limited to a total of eight, the product cannot exceed eight digits, which is within the capacity of columns 1 to 8 of the product bank. Thus, at the end of the multiplication, columns 1 to 8 of the product bank and the corresponding columns of the readout commutator PRO represent the product.

It should be noted that the main circuits of column shift magnets 128-u, t, and h include, respectively, normally closed contacts 152a-u, t, and h. The contacts remain closed only if the coils 152-u, t, and h are not energized. Reference to Fig. 12c shows that these coils are in series with the zero coils 114-0 of the three left hand columns or the multiplier columns. If the set up of any of these columns is zero, then the coil 152 of the column is energized, opening the related 152a contacts of the column shift magnet circuit, preventing energization of the magnet 128 and coil 151 corresponding to the column in which the zero set up is made. Thus, if the units order multiplier quantity were "0," then

coil 152-u would be energized, contacts 152a-u would be open, and the magnet 128-u circuit would not form to energize magnet 128-u and coil 151-u. Consequently, contacts 151b-u would not close and the cycle counting entry circuit to enter "1" into column 10 of the product bank would not be established during the first multiplying cycle. Column 9 would also remain at zero. Nor would the group of contacts 153b-u close, so that the multiplicand would not be entered into columns 1 to 5 of the product bank. When cam contacts A3 closed during this first multiplying cycle, switch SW-#2 would be advanced to position "2."

If, instead of entering "0" into any multiplier column of the value retaining bank, the operator had depressed the space bar to space to the next column, the main and stick circuits for coils 114 of the column for which the space bar had been operated would not form. Consequently, the coil 125, if the hundreds order multiplier column had been skipped; or the coil 130, if the tens order multiplier column had been skipped; or the coil 134, if the units order multiplier column had been skipped, would not be energized and their corresponding 133b, 133b, and 134b contacts would not be closed. With contacts 153b open, the main circuit of magnet 128-h and coil 151-h cannot form through position "3" of switch SW-#2; with contacts 133b open, the main circuit of magnet 128-t and coil 151-t cannot form through position "2" of the switch; and with contacts 134b open, the circuits of magnet 128-z and coil 151-u cannot be made through position "1" of the switch. Thus, if a space bar operation has been effected for any of the multiplier columns of the value retainer bank, the entry of the multiplicand and the advance of column 10 of the product bank cannot take place, and the switch SW-#2 is stepped along to the next position.

Thus, when either a zero set up in a multiplier column of the value retaining bank has been made or the column has been skipped by a space bar operation, the column shift magnet 128 and coil 151 corresponding to the multiplier column are not energized, and switch SW-#2 advances to the next position.

Restoration of switch SW-#2.—During the last multiplying cycle, when columns 9 and 10 of the product bank matched, switch SW-#2 was advanced to position "4." When this occurs, the following circuit forms (Fig. 12e):

Release magnet SWR-2.—Line 162, in parallel through magnet SWR-2 and coils 156 and 151, segment 68-4 of switch SW-#2, feeler 32, the common 34, contacts 153a, line 101.

Coil 153 immediately opens contacts 153a to eliminate any possibility of the formation of a magnet 128 (and coil 151) circuit upon the wiping of the switch segment by feeler 32 as it returns to home position. Simultaneously with the opening of contacts 153a, contacts 153b are closed. With the feeler of switch SW-#2 still away from home position, contacts SWa-2 (Fig. 2) of this switch are closed and with contacts 153b also closed, the following stick circuit for magnet SWR-2 and coils 151 and 152 is formed (Fig. 12e):

SWR-2 stick circuit.—Line 162, in parallel through magnet SWR-2 and coils 151 and 152, contacts 153b, contacts SWa-2, line 101.

When the switch feeler reaches home position, contacts SWa-2 open, breaking the above stick circuit.

When coil 151 is energized, it opens contacts 75

131a in the common return line of the stick circuits of the value coils 114 (see Fig. 12c). As a result, the setting of the five right-hand or multiplicand columns of the value retainer bank is cleared. The three left-hand or multiplier columns already were cleared during the multiplying cycles, due to successive opening of the 128a contacts and their companion A1, A2 and A3 cam contacts.

When multiplication is completed, coil 151 is energized, as explained above, and contacts 151a open to break the stick circuits of value coils 114, causing deenergization of magnet 128. Contacts R12 in the switch SW-#2 stepping circuit open, preventing advance of switch SW-#2 from its home position to which it has been restored.

Also, contacts R14 (Fig. 11f) open, breaking clutch circuit #1. If this occurs during the first or second accumulator cycle of a series, the calculator shaft continues in operation, because of the clutch shunt circuit, to the end of the third accumulator cycle of the series, as explained before. If the multiplication is completed during the third accumulator cycle of the series, the breaking of clutch circuit #1 causes the calculator unit to stop at the end of the series.

Auto typing of product

The auto typing of the debit product requires two precedent conditions: one, completion of multiplication; two, the arrival of the amount section of the bill at typing position as a result of a tab key operation following typing of the description. Similarly, auto typing of a computed credit or credit product requires completion of multiplication and the tabular spacing of the credit section of the bill to typing position. For the present, the auto typing of a debit product only will be considered.

The satisfying of the two conditions for readout of a debit product causes a circuit to form through coils 149 and 151 (Fig. 12c). In order to make clear the requirements for completing the circuit of coils 149 and 151, their circuit is traced below (see Fig. 12e):

Coils 149 and 151 circuit.—Line 101, coils 149 and 151, contact 103a, contacts 103a, contacts 152a, cam contacts R2, line 101.

Contacts 103a are closed only when multiplication is completed, in a manner which will be explained later. Contacts 103a do not open except when dealing with a credit product. Contacts 152a close when the amount section of the bill is tabulated to typing position and in accordance with the timing imposed by cam contacts R12 (Fig. 11b). Cam contacts R12 close briefly near the end of the first accumulator cycle of a series of three coextensive with a readout cycle. Thus, if multiplication is completed and the amount section of the bill tabulated to typing position during the second or third accumulator cycle of a series coextensive with a readout cycle, the open condition of cam contacts R12 prevents the completion of the coils 149 and 151 circuit, and readout cannot begin till the next readout cycle.

The closing of contacts 103a is dependent on the closure of cam contacts R12 (Fig. 11b) and on the switch SW-#3 being brought to position "6" (see Fig. 12f) by a tabular spacing operation after the description has been typed. Cam contacts R12 open shortly after the "5" point of the first accumulator cycle of a series coextensive with a readout cycle begins. Thus, if the switch SW-#3 is brought to switch position "6" before

the "5" point of the first accumulator cycle, then contacts 162a will be closed before cam contacts R2 close, and if contacts 160a also close during the same accumulator cycle as a result of completion of multiplication, then the coils 149 and 161 circuit is established, causing readout of the product to begin at column "8" point of the readout cycle. If, however, the switch SW-#3 is brought to position "6" after cam contacts R12 open during the first accumulator cycle of a series coextensive with a readout cycle, then the reclosing of contacts R12 does not occur till the next accumulator cycle and after cam contacts R2 open. Thus, although contacts 162a will be closed during the latter readout cycle, the cam contacts R2 will be open and the coils 149 and 161 circuit will not be completed, so that readout will not occur during this readout cycle but will be deferred until the next readout cycle occurs and at a time controlled by closure of cam contacts R2 in the latter cycle.

In above manner, the cam contacts R12 prevent readout of a debit from beginning at the "8" column point of a readout cycle if the multiplication has been completed during the first accumulator cycle and the tab key has not been depressed before the "5" point of the latter accumulator cycle, and readout is deferred to the next readout cycle. The purpose of this delay is to insure sufficient time for the amount section of the bill to be brought to typing position before the product can be read out into the columns of the amount section. In the absence of cam contacts R12, the coil 162 would be energized and contacts 162a would be closed as soon as switch SW-#3 reached position "6" following a tab key operation. But switch SW-#3 may take less time to advance one step than the time required for the amount section of the bill to reach the typing position as a result of the tab key operation. If switch SW-#3 reached position "6" and contacts 162a closed during the first accumulator cycle of a series after the "5" point, and multiplication were completed during the latter cycle, auto typing of the product would begin near the beginning of the next accumulator cycle. But the amount section might still be moving to typing position and its first column not yet arrived at the typing position, so that typing of the product might start while the bill still had its description section traversing typing position. This possibility is prevented by providing the cam contacts R12 to time the energization of coil 162 in the manner described above. If the tab key is depressed, after the description has been written, during the second or third accumulator cycle of a series, then with cam contacts R12 closed, the contacts 162a would be immediately closed, but since cam contacts R2 would be open, the debit product readout would not begin, in any event, until the next readout cycle, and sufficient time would be allowed for the amount section of the bill to reach typing position before auto typing began.

The closing of contacts 160a in the coils 149 and 161 circuit as a result of completion of multiplication is effected when coil 131 is energized by the release magnet SWR-2 circuit. Coil 131 closes contacts 131b to form the following circuit (Fig. 12e):

Coil 160 circuit.—Line 102, coil 160, contacts 131b, line 101;

Coil 160 closes contacts 160b to form a stick circuit extending through product bank reset contacts RMa-P (also see Fig. 1) which do not

open until resetting of the product bank occurs after the read out of the product value.

The closing of contacts 162a in the coils 149 and 161 circuit is effected by energization of coil 162. During typing of the description, switch SW-#3 is in position "5" and operation of the tab key after the description is completed brings the switch to position "6." The circuit for coil 162 is then completed during the closed period of cam contacts R12, as follows (Fig. 12f):

Coil 162 circuit.—Line 101, position "6" of switch SW-#3, socket 103-6, connection 104 to socket 105-3, contacts R12, coil 162, line 102.

Coil 162 closes contacts 162b, shunting cam contacts R12, and closes contacts 162a in the coils 149 and 161 circuit.

Upon formation of the coils 149 and 161 circuit by completion of multiplication and the tabulating of the amount section of typing position, the energized coil 161 closes contacts 161a (Fig. 12e) to hold the coils 149 and 161 energized through cam contacts R1 (see Fig. 11b).

Read out cycles.—Coil 162 also closes contacts 162c to form the following clutch magnet circuit (Fig. 12f):

Clutch circuit #2.—Line 102, magnet 40, wire 145, contacts 163b, contacts 162c, contacts 160c (closed by energization of coil 160 at the end of the multiplication operation), cam contacts 30 A9, line 101.

If multiplication is completed during any of the three accumulator cycles of a series and coil 162 is energized meanwhile, the above clutch circuit will continue the calculator shaft in operation for the next series of three accumulator cycles. If the coil 162 is not energized during a series of three cycles in which multiplication is completed, the above clutch circuit does not form, and continuation of the clutch operation 40 awaits tabular spacing of the amount section to typing position with consequent energization of coil 162. Thus, if the multiplication is completed during any of the three accumulator cycles of a series and magnet 162 has not been energized, 45 the magnet RH, deenergized by completion of multiplication, permits contacts RHd to open and break clutch circuit #1, but the clutch shunt circuit causes the accumulator cycles to continue until the series is completed. The calculator shaft 36 then stops. Subsequently, upon energization of magnet 162 and closure of contacts 162c, clutch circuit #2 is formed, and the shaft 50 36 resumes operation.

Independently of contacts 162c, the clutch magnet will be energized if multiplication has been completed and coil 162 energized during the first accumulator cycle of a series. In that event, the coils 149 and 161 circuit forms and coil 149 closes contacts 149c to form the following circuit (Fig. 12f):

Coil 148 circuit.—Line 102, coil 148, contacts 149c, line 101.

Coil 148 closes contacts 148b to provide a stick circuit timed by cam contacts A11.

Coil 148 also closes contacts 148c in parallel with contacts 162c to form the circuit of clutch magnet 40.

If the multiplication is completed during the second or third accumulator cycle of a series, cam contacts R2 will not be closed and the coils 149 and 161 circuit not completed even though contacts 162a are closed. The continuation of the operation of the calculator shaft then is effected by the closure of contacts 162c to form clutch circuit #2. During the first accumulator cycle

of the next series, contacts R2 close and the coils 148 and 161 circuit established, in turn forming the coil 148 circuit, contacts 148c of which provide a clutch magnet circuit parallel to clutch circuit #2.

Clutch circuit #2 through contacts 162c remains effective while switch SW-#3 is in position "6." At the Tab point of the first read out cycle, an automatic tabular spacing operation, explained fully later, occurs to bring switch SW-#3 to position "7" and the cents field of the amount section to typing position. At this point, the clutch circuit through contacts 162c opens, but the clutch circuit through contacts 148c remains made to carry the calculator unit into a second readout cycle. During the first accumulator cycle occurring within the second readout cycle, the clutch shunt circuit takes effect to continue the clutch in operation, regardless of opening of contacts 148c near the end of the latter accumulator cycle, to the end of the second readout cycle.

In above manner, the calculator unit is caused to perform two successive readout cycles during which readout of the debit product occurs. It may be stated at this point that two readout cycles are also provided for reading out a credit product, with contacts 171c (Fig. 12f) replacing contacts 162c in the formation of clutch circuit #2, and contacts 148c performing in the same manner as described above. Also, during the reading out of a total, the shaft 38 performs two successive readout cycles, with contacts 187b (Fig. 12f) shunting contacts 163b, 148c, 162c, and 160c, to form the clutch circuit through cam contacts A8, and contacts 188b shunting contacts 187b to function to the same effect as contacts 148c in causing operation of the shaft 38 to continue for two readout cycles.

Debit Readout.—Coil 161 closes contacts 161b in the common side of the product auto type emitter circuits (see Fig. 12b).

Coil 148 opens contacts 148a in the switch SW-#2 stepping circuit (Fig. 12e). Contacts 148a in the latter circuit are opened by coil 148. As will be brought out later, the auto typing of the product results in the reclosure of contacts RHe in the latter circuit at the "1" point of the second readout cycle. But with contacts 148a opened, the switch SW-#2 stepping circuit does not form. Coil 148 is deenergized when cam contacts A11 open during the first accumulator cycle of the second readout cycle. This occurs after cam contacts A5 in the switch SW-#2 stepping circuit have opened, so that during this first accumulator cycle, the latter circuit cannot form. During the second, following accumulator cycle, contacts RHe reopen before cam contacts A5 make, as will be explained further hereinafter, and the circuit through magnet SWM-#2 cannot then form even though contacts 148a and 148a have since closed. The switch SW-#2 is thus prevented from advancing from home position during the readout cycles in which the product is auto typed.

Coil 148 also closes contacts 148b which are in parallel with contacts 110a (Fig. 12e) and replace the latter in forming the circuit of coil 111. Coil 111 closes contacts 111a (Fig. 12a) to condition the calculator unit for entering the product, as it is auto typed, into the value retaining means.

To recapitulate, the value retaining bank has been cleared, the product bank is carrying the debit product obtained by multiplying the value in the quantity columns of the bill by the value

in the price columns, the calculator cycle shaft 38 is in operation, coil 160 (Fig. 12e) is energized, the first column of the amount section of the bill is in typing position, coils 149 and 161 (Fig. 12e) are energized, contacts 161b in series with the brush 80 of the product auto type emitter E-P (Fig. 12b) are closed, coil 111 (Fig. 12e) is energized and its contacts 111a closed (Fig. 12a), and coils 148 and 162 (Fig. 12f) are energized.

The auto readout of the product requires the closure of contacts 161b in series with the brush of product emitter E-P (Fig. 12b). The closure of contacts 161b is effected by energization of coil 161 in the coils 149 and 161 circuit, the formation of which has been explained above. The coils 149 and 161 circuit may be established during the first accumulator cycle of a series provided the switch SW-#3 is advanced to switch position "6" before the "5" point of the latter cycle and provided further that multiplication is completed during this cycle. The auto readout will then begin at point "3" of the readout cycle in which the first accumulator cycle lies. If the coils 149 and 161 circuit is not completed during the first accumulator cycle of a series, the auto readout begins at point "3" of the next readout cycle.

The "8," "7," "6" . . . "2," "1" segments of emitter E-P correspond to columns or orders of the product bank. Assuming that there is the significant value "3" in column 8 of the product bank, when the brush of emitter E-P reaches spot "8," the following circuit forms (Fig. 12b):

Product auto typing circuit.—Line 101, make and break contacts 83, contacts 161b, brush 80 of emitter E-P, spot "8" thereof, a pair of normally closed column reduction relay contacts 184a, the normally closed right side of the connected discount relay points 165a-8, the collector ring of column 8 of the readout commutator PRO, the brush 51 engaged therewith, the segment 53-3 on which the brush is resting, wire 166-3, connection b-14 (continue with Fig. 12a) key solenoid 30-3 (also see Fig. 9), connection b-8, pick up relay coil 167, line 102.

Energization of solenoid 30-3 operates typewriter key 10-3 to print a "3" in the first or highest order column of the amount section of the bill.

Coil 167 is the pickup coil of a duo wound magnet, such as disclosed in Patent 1,987,343, and its energization by the above circuit closes contacts 167a to form the following circuit through the compansion holding coil 167' (Fig. 12a):

Holding coil 167' circuit.—Line 102, coil 167', contacts 167a, contacts 161c (coil 161 is now energized by the coils 149 and 161 circuit), line 101.

Coil 167' when energized, holds contacts 167a and 167b in operated condition. It is to be understood that hereinafter any other duo wound relay magnet such as magnet 167-167' is indicated by applying the same reference designation to its pickup and holding coils with the holding coil distinguished by priming the common reference designation. For convenience, the relay contacts of the duo wound magnets are identified by the common reference designation, unprimed, supplemented by lower case letters. As brought out before, coil 167' has been energized and contacts 167b are in shifted condition in which the normally open side of contacts 167b, wired through connection b-16 to the zero solenoid 30-0 (Fig. 12a) is closed and the normally closed side, wired through connection b-32 to the space bar solenoid 30-SP is open. Thus, the

typing of a significant figure has connected one side of contacts 167b to the zero key solenoid and disconnected the other side from the space bar solenoid. The position of contacts 167b determines whether a zero readout of a dollars order column of the readout commutator should be routed to the zero key solenoid or to the space bar solenoid. If, for example, the highest order in column 8 of the product commutator PRO had been in zero position, the product readout circuit would be as follows (Fig. 12b):

Dollars order zero product readout.—Beginning as in the previous readout circuit and continuing from brush 51 of column 8 to the segment 53-0, line 168-0, wire 168 (continue with Fig. 12a), the center blade of contacts 167b, the normally closed right side of these contacts, connection b-32, solenoid 30-SP, common wire 169, connection b-10 line 102.

The energization of solenoid 30-SP operates the space bar to space the next column of the amount section of the bill to typing position. In this manner, the presence of zeros, in the dollars orders of the commutator PRO, which precede the first significant figure do not result in the typing of zeros but in space bar operations to space the corresponding columns of the dollars field of the amount section past the typing position. The presence of the first significant dollars digit in the commutator PRO causes energization of coils 167 and 167' and shifting of contacts 167b to disconnect these contacts from the space bar solenoid and to connect them, instead, to the "0" key solenoid. Thus, if column 8 has a significant figure, the left side of contacts 167b will be closed and a zero readout circuit from column 7 of the product bank will be routed through connection b-11 to the zero solenoid 30-0. Thus, a zero will be typed in the second column of the amount section when a significant digit has been typed in the preceding or first column.

It is desired to print zeros in the cents columns of the amount section, whether or not preceded by a significant digit. Accordingly, the common zero segment 53-0 of the cents order columns, or columns 1 and 2 of the product bank, is not connected to the other zero segments, but is connected through a wire 170 (see Figs. 12b and 12a in order) directly to connection b-11 which leads to zero solenoid 30-0. The condition of contacts 167b thus has no influence on the zero readout of the cents columns of the product bank, and if a zero occurs in a cents order of the product, even if not preceded by a significant digit, a zero will be typed in the corresponding cents order column of the amount section of the bill.

Automatic tabular spacing.—Between the units dollars order column of the amount section and the next or tens of cents column, it is usually desired to provide extra spacing, and this is done in the present case by an automatic tabular key operation controlled by the auto type emitter E-P. Of course, if the extra spacing between the dollars and cents fields should not be desired, then the automatic tabular spacing operation would be omitted. The automatic tabular spacing operation is initiated by engagement of the brush 80 of emitter E-P with a tab spot which follows the "3" or units dollars order spot. The tab spot is spaced from the following spot "2" twice the normal amount between successive spots in order to provide ample time for this tabular spacing operation to be completed before the readout of the tens of cents order of

the product begins. The auto tab circuit is as follows: (Fig. 12b):

Auto tab circuit.—Line 101, make and break contacts 83, contacts 161b, the brush 80 of emitter E-P, the tab spot, connection b-21 (continue with Fig. 12a), solenoid 30-tab, wire 169, line 102.

Energization of solenoid 30-Tab effects operation of the Tab key to tabular space the first cents column of the amount field of the bill to typing position.

The tens and units of cents values are then readout in succession.

Resetting of the product bank.—After passing the "1" spot of emitter E-P, corresponding to the units cents order, the brush 80 engages a Reset spot, causing the following circuit to form (Fig. 12b):

Product bank reset circuit.—Beginning as in the preceding readout circuits and proceeding from the brush 80 through the Reset spot, connection b-51 (continue with Fig. 12a), the full line position of product bank reset switch SW-PR, connection b-50 (return to Fig. 12b), reset magnet RM-P, line 102.

Energization of magnet RM-P causes zeroizing of the product bank. During the resetting operation, reset contacts RMa-P (see Fig. 1) are opened. The opening of these contacts breaks the stick circuit of coil 160 (Fig. 12e).

Automatic carriage return.—Means are provided to automatically bring the beginning of the next line of the bill to the printing position after the automatic typing of the product on one line has been completed. The automatic carriage return occurs as the feeler of emitter E-P wipes the Reset spot. The auto carriage return circuit is as follows (Fig. 12b).

Auto carriage return.—Beginning as in the Product bank reset circuit and continuing from connection b-51 (Fig. 12a) through normally closed relay contacts 171a to connection b-51, carriage return solenoid 30-CR, connection b-66, line 102.

Energization of solenoid 30-CR effect carriage return and accompanying line spacing operation.

Entry of product into total bank

The product is entered into the total bank which accumulates the debits and credits. All values typed into the amount or credit section of the bill are entered as a result of the typing thereof into the total bank. Thus, any error which occurs in the typing will cause a corresponding error in the balance standing in the total bank, and may be checked back by reference to the values typed in the amount and credit sections of the bill.

Before auto typing of the product began, the coil 111 circuit was established through contacts 149b (Fig. 12e). Thus, contacts 111a (Fig. 12a) are closed during auto typing operation and the depression of the digit keys will result in the setting up of the value retainer bank (Figs. 12c and d) to represent the typed values, in the same manner as when the quantity and price values were typed. The entry of the right-hand or units of cents digit of the product into the right-hand column of the retainer bank causes energization of magnet R.H. This occurs at the "1" point of the second effective readout cycle. At the following Reset point, the product bank is reset, automatic carriage return takes place, and as a result of the opening of reset contacts RMa-P, the coil 160 circuit (Fig. 12e) is broken, all as ex-

plained before. When cam contacts R1 open during the second effective readout cycle, the stick circuit of coils 148 and 181 is broken. Consequently, contacts 149b in the coil 111 circuit (Fig. 12e) reopen to deenergize the latter coil; contacts 148a in the switch SW-#2 stepping circuit reclose, and contacts 181b in the common side of the product auto type circuits open. When cam contacts A11 open during the first accumulator cycle lying within the second effective readout cycle, the stick circuit of coil 148 (Fig. 12f) breaks, and contacts 148a in the switch SW-#2 stepping circuit reclose. At this point, contacts RHe (Fig. 12e) in the latter circuit are closed because magnet RH is energized. But cam contacts A5 open before cam contacts A11 break so that contacts 148a are still open while cam contacts A5 are closed and, consequently, the switch SW-#2 stepping circuit does not form. During the next accumulator cycle, the contacts RHe will open, as will be brought out further on, so that the latter circuit also does not form during the remainder of the second effective readout cycle.

Magnet RH is energized at the "1" column point of the second effective readout cycle, closing contacts RHf (top of Fig. 12f). After the entry period of the accompanying accumulator cycle, cam contacts A7 (Fig. 11a) close. At this point, coil 148 is still energized and contacts 148d are closed. With cam contacts A7, contacts RHf, and contacts 148d closed, a circuit is formed through total entry relay magnet 130 as follows (Fig. 12f, at top).

Total entry relay magnet.—Line 102, magnet 130, contacts RHf, 148d, cam contacts A7, line 101.

Magnet 130 closes contacts 130c to form a stick circuit for the magnet, extending through cam contacts A8 which do not open until after the entry period of the following accumulator cycle.

Energization of magnet 130 closes the left, normally open sides of the 130b group of contacts (see Fig. 12d) and opens the normally closed sides. The opening of the latter sides disconnects the columns of contacts 114b of the value retainer bank from the product bank columns, while the closing of the left sides of contacts 130b connects the columns of 114b contacts to the columns of the total bank ACC-T. All this occurs during the first accumulator cycle of the series coextensive with the second effective readout cycle. During the next accumulator cycle, the setting of the bank of 114b contacts, representing the automatically typed debit product, is converted into entries of the product into the total bank. Assuming, for instance, that the highest order, or the first column from the left, of the value retainer bank is set to represent "5," then the debit total entry circuit is as follows (Fig. 12d):

Debit total entry circuit.—Line 101, make and break contacts 75, contacts 154a (closed except when a credit item is involved), the brush 77 of emitter E+, spot "5," the common wire 156 of the row of 114b-5 contacts, the closed 114b-5 contacts of the left-hand column, the common wire 157 of the left-hand column of contacts, the left, now closed side of the pair of total entry contacts 130b in series with this common wire 157, magnet CM of column 8 of the total bank, line 102.

In a similar manner, total entry circuits will be formed through the other columns of the total bank, and at the end of the entry period of the second accumulator cycle within the second effective readout cycle, the product will have been

read out from the bank of 114b contacts into the total bank.

When cam contacts A10 open during the latter accumulator cycle, the common side of the stick circuits of the columns of value coils 114 is opened, parallel contacts 130a having previously been opened by energization of total entry relay magnet 130. The value retaining bank is thus cleared after the product has been entered into the total bank.

Credit items

The credit items are either a simple credit, which includes a payment by cash or check (see line 12 of the bill, Fig. 13), or a computed credit, which is the product of factors typed in the quantity and price columns. The computed credit may be the product of returned articles by the individual price of the article (see item 8 of Fig. 13) or the product of equivalent factors, or may be a discount. The discount involves the multiplication of the percentage discount by the amount on which the discount is to be taken. The amount to be discounted may be a previously ascertained value (see item 2 of Fig. 13) or may be a balance taken from the total bank (see items 9, 10 and 11 of Fig. 13).

The typing and entry of a computed credit item, such as item 8 of the illustrative bill (Fig. 13) will be explained first.

Computed credit operations.—It will be assumed that the eighth item of the bill, Fig. 13, is to be typed and entered. The operator proceeds, in exactly the same manner as explained for a debit item, in the typing of the lot number, quantity, price, and description. The typing of the quantity and price causes setting of the value retainer bank, and multiplication begins after entry of the last price digit and continues during the typing of the description. Before depressing the tab key following typing of the description, the operator depresses the credit key CK (see Fig. 1). Depression of key CK closes key contacts CKa and CKb (bottom of Fig. 12a). It will be recalled that the multiplication operation involves the multiplication of the price factor or multiplicand by successive orders of the quantity factor or multiplier and that at the end of the multiplication by the last order of the multiplier, the switch SW-#2 is advanced to position "4," causing formation of the release magnet SWR-2 circuit. In this circuit are also coils 131 and 153 (see Fig. 12e). Coil 131 opens contacts 131a in the common side of the stick circuits of the value coils 114 (Fig. 12c), as a result of which coil 138 in the stick circuit of the right hand column of value coils is deenergized. Assuming now that multiplication has been completed, coil 138 will be deenergized and relay contacts 139a (middle, left of Fig. 12f) will be in normal condition, with the left side closed and the right side open. The condition of the relay contacts 139a determine whether credit relay coils 155, 150, and 172 are ready to be energized upon depression of the credit key CK. With contacts 139a in normal condition, the closure of credit key contacts CKa establishes the following circuit (Fig. 12f):

Credit coils circuit #1.—Line 102, coils 155, 150, 172, the left side of contacts 139a, connection b-45 (continue with Fig. 12a), contacts CKa, connection b-46 (return to Fig. 12f), wire 173, normally closed 132b relay contacts, connection b-55 (return to Fig. 12a), normally closed error key contacts EKb, connection b-56, line 101.

If multiplication had not been completed at

the time the credit key was depressed, the above circuit would not form because the left side of contacts 139a still would be open. Instead, the following circuit would be completed (Fig. 12f):

Credit coil 174 circuit.—Line 102, coil 174, the 5 right, still closed side of contacts 139a, and from there on as in the preceding circuit.

Coil 174 closes stick contacts 174a to maintain the coil energized, after release of the credit key and opening of its contacts CKa, through the 10 following circuit (Fig. 12f):

Credit coil 174 stick circuit.—Line 102, coil 174, contacts 174a, wire 113, contacts 132b, and from there on as in the credit coils circuit #1.

Coil 174 closes contacts 174b to prepare the 15 credit coils 150, 155, and 172 for energization as soon as multiplication is completed and obviates the necessity for the operator to continue holding the credit key down. When multiplication is subsequently completed, the left side of contacts 139a 20 closes and the following circuit forms (Fig. 12f):

Credit coils circuit #2.—Line 102, coils 155, 160, 172, the left side of contacts 139a, contacts 174b, line 113, contacts 132b, and from there on as in the credit coils circuit #1.

Coil 172, when energized by either credit coils circuit, closes contacts 172a to directly connect the credit coils 150, 155, and 170 to contacts 132b, and these coils then remain energized until contacts 132b open or unless the error key EK (see Fig. 1) is depressed to open normally closed error key contacts EKb (Fig. 12a).

When the credit key CK was operated, it also closed credit key contacts CKb (Fig. 12a) to establish the following circuit (Fig. 12f):

Credit coil 163.—Line 102, coil 163, connection b-47 (turn to Fig. 12a), contacts CKb, connection b-48, connection b-55, error key contacts EKb, connection b-56, line 101.

Coil 163 closes contacts 163c to provide a stick circuit as follows (Fig. 12f):

Credit coil 163 stick circuit.—Line 102, coil 163, contacts 163c, normally closed relay contacts 171a, connection b-55 (turn to Fig. 12a), error key contacts EKb, connection b-56, line 101.

Coil 163, while energized, holds contacts 163b in clutch circuit #2 (Fig. 12f) open to prevent formation of this circuit until the credit section of the bill is brought to typing position. Coil 163 also opens contacts 163a in the coils 149 and 161 circuit (Fig. 12e) to prevent energization of these coils, which initiates auto readout and typing of the product, until the credit section is reached. It will be recalled that when the amount section of the bill is tabulated to typing position, coil 162 is energized and closes contacts 162b in the coils 149 and 161 circuit to initiate the reading out of the debit product into the amount section. When dealing with a credit item, the credit key is depressed and coil 163 energized to open contacts 163a in the coils 149 and 161 circuit. Consequently, after typing the description, when the operator tabulates to the amount section, the closure of contacts 162b will not complete the coils 149 and 161 circuit, and the credit product will not be read out into the amount section. The operator must then depress the tab key twice to tabulate the first column of the credit section to typing position. This advances switch SW-#3 (Fig. 12f) from position "6" to position "8," causing the following circuit to form (Fig. 12f).

Coil 177 circuit.—Line 101, position "8" of switch SW-#3, socket 103-8, plug wire 104 to socket 105-4, coil 177, line 102.

Coil 177 opens contacts 177a in the credit coil 163 circuit, deenergizing coil 163 to permit contacts 163a and 163b, respectively in the coils 149 and 161 circuit and clutch circuit #2, to reclose.

The formation of the coils 149 and 161 main circuit (Fig. 12e) through contacts 162a cannot occur because the coil 162 is not now energized. Coil 177, instead, is now energized and closes contacts 177b, in parallel with contacts 162a to replace the latter in the coils 149 and 161 circuit. When multiplication is completed, coil 131 is energized by the release magnet SWR-2, circuit, coil 131 closes contacts 131b to complete the coil 160 circuit, and energization of coil 160 is then maintained through the stick circuit extending through reset contacts RMa-P. Coil 160 closes contacts 160a in the main circuit of coils 149 and 161. With contacts 160a, 163a, and 177b closed, when cam contacts R2 also close (see Fig. 11b), the circuit of coils 149 and 161 is completed. Coil 161 closes contacts 161a to form the stick circuit of the coils through cam contacts R1.

To recapitulate, the formation of the coils 149 and 161 main circuit, after depression of the 25 credit key, requires completion of multiplication with resultant closure of contacts 160b, and requires the tabular spacing of the credit section of the bill to typing position, resulting in energization of coil 177 to close contacts 177b and to open contacts 177a to break the circuit of coil 163 and cause contacts 163a to reclose. The completion of multiplication, together with operation of the credit key, causes the formation of a circuit through credit coils 150, 155, and 172 (Fig. 12f). Thus, at this point, coils 160, 149 and 161, 177, 150, 155, and 172 are energized.

When coil 163 was deenergized, contacts 163b in the circuit of clutch magnet 40 (Fig. 12f) reclosed. Coil 177, now energized, closes contacts 177c in series with contacts 163b, and energized coil 160 closes contacts 160c. With all these contacts closed, a circuit through clutch magnet 40 is completed, similar to clutch magnet circuit #2. Coil 149, now energized, closes contacts 148c to form the coil 148 circuit (Fig. 12f). Coil 148 closes stick contacts 148b to provide a stick circuit for the coil through cam contacts A11. Coil 148 closes contacts 148c to continue the clutch magnet energized after contacts 177c open as a result 50 of deenergization of coil 177, occurring when the tabular spacing from the dollars field of the credit section to the cents field advances switch SW-#3 to position "9." Accordingly, two readout cycles for the credit product will be performed, just as when a debit product was read out.

Coil 161 closes contacts 161b in the common line of the product auto type emitter E-P (see Fig. 12b). The credit product is then read out through emitter E-P from the product bank by 55 formation of the product auto type circuits, which are the same for debit or credit products, and the credit product is typed in the credit section of the bill.

When coil 148 was energized, it closed contacts 60 148b to form the circuit of coil 111 (Fig. 12e). Credit coil 172 has also closed contacts 172b, in shunt with contacts 148b, but the former contacts are necessary only for the entry of a simple or cash credit, which will be explained later, during 65 which entry the coil 148 is not energized and contacts 148b are not closed. Coil 111 closes contacts 111a (Fig. 12a) to enable the credit product, while being typed into the credit section, to be entered in the value retainer bank, just as when 70 a debit product was typed into the amount sec-

75 a debit product was typed into the amount sec-

tion. The purpose of setting up the value retainer bank with the typed product is to control entry of the product into the total bank. The debit product was entered into the total bank additively. The credit product must be entered subtractively through credit emitter E- (Fig. 12d) into the total bank, and entry through the debit emitter E+ must be prevented. The common side of the entry paths through emitter E+ includes contacts 154a closed by normally energized coil 154, as explained before. When a credit item is being dealt with, the credit coils 150, 155, and 172 are energized in the manner explained above. Coil 155 opens contacts 155a in the coil 154 circuit (Fig. 12f), deenergizing coil 154 and causing contacts 154a to open, thus breaking the connection of emitter E+ to line 101. Coil 155 also closes contacts 155b, connecting the feeler of credit emitter E-, through make and break contacts 75, to common line 101.

Energized coil 148 has closed contacts 148d (top of Fig. 12f) and entry into the right-hand column of the value retainer bank of the units of cents product digit has energized magnet RH to close contacts RH/ in series with contacts 148d. The cam contacts A7 then close and the main circuit of total entry magnet 138 is formed, followed by the stick circuit extending through contacts 138c and cam contacts A8. Energization of magnet 138 shifts the center blades of the group of 138b contacts (Fig. 12d) to connect the columns of 114b contacts to the total bank. As shown in Fig. 12d, the credit emitter E- has its spots "8" to "1" respectively connected by wires 178 to complementary spots "1" to "8" of the plus emitter E+. Thus, when the plus emitter is operative to cause entry through the retainer relay bank of b contacts into the total bank, the plus value of the amount represented by the position of the closed 114b contacts is entered. When the credit emitter is operative, the entry through the same closed 114b contacts is in complementarily timed relation to the amount represented by the closed 114b contacts, so as to enter the "9" complements of the amount into the total bank. Assume, for example, that the highest or eighth order of the credit amount contains digit "5," now represented by closed contacts 114b-5 of the left-hand column. The credit entry circuit then is formed at the "4" point of the accumulator cycle, as follows (Fig. 12d):

Credit entry circuit.—Line 101, contacts 75, contacts 155b, the brush of the credit emitter E-, spot "4" thereof, connection 178 to common wire 156 of the row of 114b-5 contacts, closed, contacts 114b-5 of the left-hand column, the left side of the connected pair of 138b contacts, magnet CM of column 8 of the total bank, line 102.

Thus, the "nine" complement "4" of the credit digit "5" is entered into the total bank.

Through similar circuits, the complements of the other digits "1" to "8" of the credit amount are entered into the total bank. When a credit digit "0" has been set up in the value retainer bank, the credit entry circuit enters the complement "9," as follows:

Complement of "0" credit entry.—Line 101, contacts 75, contacts 155b, the brush of emitter E-, the "9" spot thereof, contacts 155c, the closed 114b-8 contacts, the left side of the connected contacts 138b, the related magnet CM of the total bank, line 102.

If a space bar operation is effected to skip entry into a column of the value retainer bank, then a value coil stick circuit for this column will not

be formed. In the stick circuits of the several columns are coils 125, 133, 134, 135, 136, 137, 138, and magnet RH (see Fig. 12c). Failure of any of these coils or of magnet RH to be energized causes associated contacts 125c, 133c, 134c, 135b, 136b, 137b, 138, or RHg (top of Fig. 12d) to remain closed. When dealing with a credit set up, the value "9" is entered into the total bank column connected to that value retainer column in which one of the latter contacts remains closed because of the space bar operation which skipped entry into this value retainer column. For example, if the left-hand value retainer column has not been set up, contacts 125c remain closed, and "9" will be entered in column 8 of the total bank through a circuit which begins the same as the preceding circuit, but branches off from contacts 155c to a wire 180 contacts 125c, the common wire 137 of the left-hand column, the left side of connected contacts 138b, magnet CM of column 8 of the total bank, line 102.

In above manner, when a column of the value retainer bank has not been set up because the corresponding credit column of the credit section has been left blank, the value "9" is entered into the corresponding total bank column just as though a zero had been typed in the credit column.

If the credit digit in a denominational order is "9," the complement "0" need not be entered as it would not affect the result.

The elusive one is entered into the units order by energization of the elusive one magnet ELM (see Fig. 4) through the following circuit (Fig. 12f):

Elusive "1" magnet circuit.—Line 101, cam contacts A8 (see Fig. 11a), credit relay contacts 158b, total entry relay contacts 138d, magnet ELM, line 102.

Magnet ELM unlatches element 55 (Fig. 4) from the arm 58 of the units order of the total bank, and the arm moves to the left to be subsequently returned by carry bail 80 during the carry over period of the cycle for adding the elusive one to the units order of the total bank, as explained hereinbefore.

The typing of the units of cents credit digit causes energization of coil 139 of the stick circuit of the right-hand column of value coils 114 (Fig. 12c). Coil 139 closes contacts 139b to cause entry of a "9" into column 9 of the total bank as a manifestation of a credit entry. When the brush of the credit emitter wipes the "9" spot, a circuit is established which begins as in the other credit entry circuits and proceeds from the "9" spot of emitter E- through contacts 138b, magnet CM of column 9 of the total bank, and to line 102. This results in entry of "9" into column 9 of the total bank.

When the brush of the credit emitter wipes the "0" spot, the following circuit forms (Fig. 12d):

Coils 132 and 142 circuit.—Line 101, contacts 75, contacts 155b, brush 77 of emitter E-, spot "0," wire 181 (continue with Fig. 12e), total entry relay contacts 138e (now closed), coils 132 and 142, line 102.

Coil 132 closes contacts 132c to provide a stick circuit extending through cam contacts A4 (see Fig. 11a).

Coil 132 opens contacts 132a common to the stick circuits of value coils 114 (Fig. 12c).

Coil 132 also opens contacts 132b common to the circuits of credit coils 150, 155, 172, and 174 (Fig. 12f), causing deenergization of these credit coils.

Coil 142 opens contacts 142a in the coil 111 circuit #2 (Fig. 12e), which was formed as a result of closure of contacts 134b when coil 134, in the third value retainer column from the left (Fig. 12c), was energized. The auto carriage return circuit also formed during the typing of the credit product, bringing the beginning of the next line to typing position.

Simple credit item

The next to last line of the illustrative bill (Fig. 13) shows a simple credit item, which does not involve entry into the quantity and price sections. The operator, in making the simple credit entry on the bill, tabulates the description field of the bill to typing position and types the description. After typing the description, the operator, by repeated depressions of the tab key, brings the credit section of the bill to typing position. The credit key is depressed after the description is typed and before or after tabulating the credit section to typing position but prior to typing of the simple credit. When the credit key is depressed, the credit coils 150, 155, and 172 are energized by credit coils circuit #1.

Coil 150 opens contacts 150a in the switch SW-#2 stepping circuit to prevent operation of this switch when contacts RHe subsequently close as a result of the typing of the units cents order digit of the simple credit. Coil 155 opens contacts 155a in the circuit of coil 154 (Fig. 12f) to cause the opening of contacts 154a (Fig. 12d) connecting the debit emitter E+ to line 101. Coil 155 also closes contacts 155b, connecting the credit emitter E- to line 101, and closes contacts 155c connecting the "9" spot of this emitter to the "0" row of contacts 114b and to line 180 for reading out a complement "9" from a column of contacts 114b which has either been set to represent "0" or has not received any entry.

Coil 172 closes contacts 172b (Fig. 12e), parallel with contacts 110a and 149b, to form the circuit of coil 111. Coil 111 closes contacts 111a to enable the operation of the digit keys, in typing the simple credit, to enter the credit value into the value retainer bank. Coil 172 also closes contacts 172c, in shunt with contacts 148d, to prepare the total entry magnet 130 (top of Fig. 12f) for subsequent energization.

The operator, after depressing the credit key and tabulating the credit section of the bill to typing position, types the simple credit value. During typing of this value, the coils 114 of the value retainer bank are energized, in the manner explained before. Entry of the last digit into the right-hand column of the value retainer means causes energization of magnet RH. The contacts RHd thereupon close to form clutch magnet circuit #1. Contacts RHf close, credit coil contacts 112c have been closed before, and when cam contacts A7 close, the circuit of total entry magnet 130 (Fig. 12f) is formed. Accordingly, the simple credit will be entered, during an accumulator cycle, into the total bank in the same manner as explained for the computed credit. Since there is no auto typing of a product involved in the entry of the simple credit, the auto carriage return circuit does not form, and carriage return operation is initiated by the operator.

Discount operation

The discount item is within the class of computed credit items. Line 2 of the illustrative bill (Fig. 13) shows a 25% discount allowed on the debit extension of the first item. The tens order

digit of the discount percentage is typed in the hundreds column of the quantity field, the units order percentage digit in the tens column, and the tenths order percentage digit (the closest approximation to the fraction) in the units quantity column. The amount on which the discount is allowed is typed, in the regular order, in the price columns. The multiplication of the values typed in the quantity and price columns takes place, in the same manner as described before, during the typing in the description field. After typing in the description, the operator depresses the discount key DK (Fig. 1) closing contacts DKa (Fig. 12a) to form the following circuit:

15 *Discount relay magnet.*—Line 101, connection b-64, contacts DKa, connection b-65 (turn to bottom of Fig. 12f), a relay coil 182, discount relay magnet 165, line 102.

Magnet 165 closes contacts 165b to form the 20 following stick circuit (Fig. 12f):

25 *Discount magnet stick circuit.*—Line 102, magnet 165, contacts 165b, resistance 183, contacts 142b, line 101.

The stick circuit maintains magnet 165 energized after contacts DKa open due to release of the discount key. The main circuit of magnet 165 includes coil 182 which closes contacts 182a and 182b (Fig. 12a), shunting credit key contacts CKa CKb, and thus making it unnecessary to depress the credit key along with the discount key. The closing of contacts 182a and 182b has the same effect as though the credit key were depressed and results in formation of the credit coil 163 circuit. Energization of coil 163 (Fig. 12f) opens contacts 163a in the main circuit of coils 149 and 161 (Fig. 12e) to prevent energization of these coils when multiplication is completed and the amount section of the bill brought to typing position. When multiplication is completed, credit 30 coils 150, 155, and 172 are energized in the manner explained before, and when the credit section is brought to typing position, coil 177 is energized and contacts 177a in the stick circuit of coil 163 open. Deenergization of coil 163 permits contacts 35 163a in the coils 149 and 161 circuit to reclose. Coil 177 has closed contacts 177b in the latter circuit (Fig. 12e), and contacts 160b are closed by coil 160, energized as a result of completion of multiplication. The coils 149 and 161 circuit 40 is then completed when cam contacts R2 close and is held through cam contacts R1.

The discount percentage has been typed in the 45 quantity columns and entered in the value retainer bank as a number which is the discount percentage multiplied by 1000. Thus, in the first discount item of the bill (Fig. 13), the discount percentage equals 25/100 and is entered as 250 which is 1000 times the true discount percentage. The product obtained by multiplying the discount

50 digits in the quantity columns by the number in the price columns is 1000 times greater than the true product of the discount percentage and the amount on which the discount is allowed. Before reading out the product standing in the product bank into the credit section of the bill as the true discount value, the product must be divided by 1000, or reduced by three decimal places to the left. This effect is obtained by energization of discount magnet 165 which closes the left sides 55 of the group of 165a contacts (Fig. 12a) and opens the right, normally closed sides. As indicated in Fig. 12b, the "8" column spot of the auto type emitter E-P is disconnected from column 8 of the commutator PRO because of the opening

60 bank of the right side of contacts 165a-8 and is con- 65

nected through the left, now closed side of these contacts to wire 168 which leads to the normally closed side of contacts 167b (Fig. 12a) connected to the space bar solenoid 38-SP. Thus, during the readout cycle, when the brush of emitter E-P wipes segment "8," the space bar solenoid will be energized and the first from the left, or highest order, column of the credit section skipped. Similarly, spots "7" and "6" of the emitter E-P are disconnected, by shifting of the related 168a contacts, from columns 7 and 6 of the product bank commutator and connected instead to wire 168 to form the circuit of space bar solenoid 38-SP twice in succession as the brush of the emitter successively wipes emitter spots "7" and "6." Thus, by the time the brush of the emitter reaches emitter spot "5," the fourth column from the left of the credit section, or the hundreds of dollars column, is in typing position. The "5" emitter spot is connected through the left side of contacts 168a-5 to column 8 of the product bank commutator PRO. Column 8 of the product bank is the 100,000 dollars order of the product bank. Thus, the value in the latter column of the product bank will be read out into the 100 dollars order credit section column, equivalent to reducing the product by three decimal places to the left. Similarly, the "4," "3," "2" and "1" spots of the emitter E-P are connected through the left sides of the related 168a contacts to columns 7, 6, 5, and 4 of the product bank. In above manner, the product is read out and typed as a number which is one-thousandth the value standing in the product bank, thereby giving the true discount value.

The emitter E-P ignores the three lowest orders of the product bank which carry the tenths, hundredths, and thousandths of cents digits of the discount. However, it is desired, in the event the tenths of cents value exceeds "5," to spill "1" into the units cents order. Column 4 of the product bank contains the units of cents discount digit and column 3, the tenths of cents discount value. Before emitter E-P reads out any of the columns, entry of "5" into column 3 occurs, in a manner which will be explained shortly. If column 3 previously read "4" or lower, then addition of "5" will not result in a carry over to column 4, but if column 3 read "5" or higher, then the addition of "5" results in carrying "1" into column 4. To make clear the requirements for entering "5" into product bank column 3, the circuit therefor will first be traced (Fig. 12d).

Half-cent pickup.—Line 101, contacts 75, credit relay contacts 168b, brush 77 of credit emitter E—, the "5" emitter spot, wire 185, cam contacts R8, contacts 160d, discount relay contacts 168c, column 3 magnet CM of the product bank, line 102.

Contacts 168b are closed by credit coil 155 (Fig. 12f) which is energized only upon completion of multiplication. Contacts 160d are closed by coil 168 energized upon completion of multiplication. Contacts 168c are closed by discount relay magnet 168. Cam contacts R8 are closed during the "5" point of the first accumulator cycle lying within a readout cycle. The readout of a product occurs after contacts 161b (Fig. 12b) close as a result of the formation of the coils 149 and 161 circuit which, for a credit product, requires completion of multiplication and the tabulating of the credit field of the bill to typing position, as previously explained. If the credit field has already been brought to typing position and multiplication is completed during the first accumu-

lator cycle lying within a readout cycle, then readout will begin during the same readout cycle at the "8" column point. This is not desirable during discount operations because, in that event, the half-cent pickup circuit will not have been formed since cam contacts R8 have closed and opened, without effect, during the same first accumulator cycle. Accordingly, when handling a discount item, the operator, after entering the factors, typing the description, and depressing the discount key, waits until the calculator shaft 38 and the parts operated thereby have stopped operating before tabulating the credit section to typing position. By waiting until the calculator shaft 38 has stopped operating, the operator knows multiplication has been completed and that the calculator unit is ready to begin a new readout cycle. Then, upon tabulating the credit field to typing position, the contacts 177b close to form the circuit of coils 149 and 161 (Fig. 12e) contacts 177c close to establish a clutch circuit, and two readout cycles follow, as explained previously. During the first readout cycle, the half-cent pickup circuit enters "5" into column 3 of the product bank before the product readout begins at column point "8."

The discount product is entered into the totalizer through the emitter E—, in the manner explained for the other credit items. When the "0" spot of emitter E— is traversed by the brush, the previously traced coils 132 and 142 circuit is formed, and contacts 142b open to break the stick circuit of the discount magnet 168 (Fig. 12f).

Successive discounts

Lines 9, 10 and 11 of the illustrative bill (Fig. 13) show successive discounts. These are taken on the successive balances standing in the total bank. The discount percentage is typed, as before, in the quantity columns and the balances on which the discounts are to be taken are typed in the price columns. The balances may be read by the operator from indicating wheels 47 (Figs. 1, 3, and 4) of the total bank. However, to take care of the possibility that a total bank of the concealed type may be used, provision is made for printing the balances in the total section of the bill without clearing the total bank. The operator then is enabled to read the typed total and enter it in the price columns of the next line as the amount to be multiplied by the discount percentage. An additional advantage in this procedure is that a check is provided of the accuracy of the entry of the balance in the price columns by the operator.

The discount operations are the same for each of the successive discounts as for the single discount explained previously. The only difference between the successive discount items and the single discount item is in the printing of the balance, standing in the total bank, on the line preceding the line on which a successive discount item is typed, and the means for printing the balance will be explained in connection with the total taking operations.

Total operations

The total bank carries the accumulation or balance of the debit and credit items entered on the bill. This total may be read out and automatically typed in the total section of the bill. The total read out operation requires the depression of either total key TK or TRK (Fig. 1) and the tabular spacing of the carriage to bring the total section to typing position. The key TK is

used if the total is to be read out without accompanying reset of the total bank, while the key TRK is used when it is desired to take the total and also reset. For example, the key TK is used when taking the total for successive discount purposes, or when two bills are to be sent to the same customer, with the total of the first bill to be carried forward to the second bill.

Total taking without resetting.—Assuming that it is desired to take a total without resetting, the operator depresses the total key TK, closing contacts 'TK' to form the following circuit (Fig. 12a):

Total key circuit.—Line 101, connection b-44, contacts 'TK', connection b-42 (turn to Fig. 12f), coil 171, line 102.

Coil 171 closes contacts 171b to maintain the coil energized through relay contacts 186a. The latter contacts do not open until after the total relay coils circuit is established, as will be explained below. Coil 171 also closes contacts 171c (Fig. 12f) in the line leading to plug socket 105-5, which is connected to plug socket 103-10, corresponding to the total section. Nothing further happens until the operator tabulates the total section to typing position. When this is done, switch SW-#3 advances to position "10," and with contacts 171c closed, the following circuit forms (Fig. 12f):

Coil 187 circuit.—Line 101, position "10" of switch SW-#3, socket 103-10, the plug wire 104 to socket 105-5, contacts 171c, coil 187, line 102.

It is to be noted that the above circuit requires operation of the total key and also tabular spacing of the total section to typing position, the order in which the operations are effected being immaterial. However, at this point, it may be explained that when it is desired to type the total on the same line as the last item, the total key is depressed before the carriage is tabulated to the amount section if a computed debit is involved or to the credit section if a computed credit is involved. This prevents formation of the auto carriage return circuit which normally follows the readout of the computed debit or credit amount. When the total key is depressed before the carriage is tabulated to the amount or credit sections, the coil 171 is energized, opening contacts 171a (Fig. 12a) of the auto carriage return circuit, and, consequently, after the auto typing of the debit or credit amount, the same line of the bill remains in position to receive the total typing. If the item on the last line of the bill is a simple or cash credit, then auto typing is not involved and the auto carriage return circuit does not form, so that the depression of the total key may take place after the manual typing of the simple credit and the total may be printed along the same line, if desired. If it is desired to type the total on the line following the last item line, the total key is not depressed until after the computed credit or debit has been typed and the automatic carriage return operation completed.

As a result of operation of the key TK, the total key circuit, energizing coil 171, has been established, and when the total section is tabulated to typing position, the coil 187 circuit also forms.

Coil 187, upon energization, closes contacts 187a to by-pass contacts 171c and maintain the coil energized while the switch SW-#3 remains in position "10." Coil 187 also closes contacts 187b to establish a circuit for clutch magnet 40 (Fig. 12f) extending through contacts A9 to initiate two readout cycles of calculator shaft 36. During the first readout cycle, cam contacts R4 (see Fig.

11b) close and, with contacts 187c also closed by the energized coil 187, the following circuit forms (Fig. 12e):

Total relay coils circuit.—Line 101, cam contacts R4, contacts 187c, total relay coils 117, 186, and 188, line 102.

Coil 117 closes stick contacts 117b to hold the total relay coils energized through cam contacts R3.

Coil 186 closes contacts 186b (Fig. 12f) in parallel with contacts 187b in the clutch magnet circuit. During the first readout cycle, at the Tab point, the bill sheet is tabulated to bring the cents field of the total section to typing position. However, in the present illustrative embodiment, switch SW-#3 is not advanced as a result of the tabular spacing operation from position "10" but, due to the construction of ratchet 88 (Fig. 2), remains in the latter position. Accordingly, coil 187 is maintained energized and when the clutch shunt circuit opens due to breaking of cam contacts R9 in the third accumulator cycle of the series coextensive with the first readout cycle, the clutch circuit through contacts 187b and A9 is operative to continue the shaft 36 in operation through the first accumulator cycle lying within the second readout cycle. At the Reset point of the latter cycle, an auto carriage return operation restores switch SW-#3 to home position and coil 187 is deenergized and its contacts 187b open, but the clutch shunt circuit continues operation of the shaft 36 to the end of the second readout cycle. The relay contacts 186b are provided in shunt with contacts 187b in the event that it is desired, for any reason, to advance the switch SW-#3 from position "10" at the Tab point of the first readout cycle. In that event, the contacts 186b will act in conjunction with cam contacts A9 to maintain the clutch operative for performing a second readout cycle.

Coil 186 also opens contacts 186a in the total key circuit (Fig. 12f) to deenergize coil 171. Coil 186 also closes contacts 186c which are in shunt with contacts 187c (Fig. 12a) to replace the latter in the holding coil 167' circuit, which forms as a result of the readout of the first significant figure, prior to which contacts 187b divert the "0" dollars readout circuit to the space solenoid 30-SP, as explained hereinbefore.

Coil 186 closes contacts 186d and when cam contacts R7 close, the following circuit forms (Fig. 12f):

Credit balance control magnet 189.—Line 101, contacts R7, contacts 186d, plural coil magnet 189, line 102.

When the total bank carries a net debit or positive balance, magnet 189 performs no function. Assuming there is a debit balance, it will suffice, for the present, to state that magnet 189 is deenergized when contacts R7 open before the beginning of the readout period at "8" of the readout cycle (Fig. 11b).

After cam contacts R7 open, cam contacts R8 close, and with contacts 117c closed by total relay coil 117, the following circuit forms (Fig. 12f):

Total control magnet 190.—Line 101, cam contacts R8, contacts 117c, magnet 190, line 102.

Magnet 190 closes the group of contacts 190a at the right of the commutator TR0 (Fig. 12b).

Coil 117 also opens contacts 117a (Fig. 12a) common to the coil 120, coil 140, and the key coil circuit to prevent any possibility of the value retaining means being set up as a result of the automatic typing of the total which is to take place.

Coil 117 also closes contacts 117d between the brush of the auto type total emitter E-T (Fig. 12b) and line 101.

Debit balance readout.—Assuming that the bill total is a plus or debit total, and that the reading in column 8 of the total bank is "5," then the total auto type circuit is as follows (Fig. 12b):

Debit total auto type circuit.—Line 101, contacts 83, contacts 117d, normally closed contacts 191a, the brush of emitter E-T, emitter spot "8," the serially connected, closed side of column reduction points 184b, the serially connected, normally closed side of relay contacts 201a, the + collector ring of column 8 of total bank commutator TRO, the + brush 51 of column 8, segment 53-5 now engaged by the + brush, the serially connected, now-closed contacts 190a, the serially connected, normally closed side of inversion relay contacts 193a-5, connection b-16 (turn to Fig. 12a), key solenoid 30-5, connection b-9, pick-up coil 167, line 102.

The solenoid 30-5 operates the key 10-5 to type "5" in the first column of the total section of the bill. The function of coil 167 is the same as described in connection with the readout of the product.

Through similar total auto type circuits, digits 1 to 8 are read out of the other total bank columns and automatically typed in total section. The readout of zeros in columns 8 to 3 of the total bank is also effected through a similar auto type circuit, but which includes closed "0" test contacts for a reason which will be made clear later. The readout of zeros from columns 1 and 2 is through a different circuit, which will be traced hereinafter. Likewise, the readout of "9" from the total bank columns is through circuits which depart somewhat from the above-traced total auto type circuit. Thus, the readout circuit for a "9" from dollars columns 8 to 3 proceeds from the "9" segments 53 of these columns through the left, normally closed side of contacts 194a to the "9" segments of columns 1 and 2, through the closed side of contacts 194b, a pair of total control relay contacts 190b, contacts 193a-9, connection b-20 (turn to Fig. 12), solenoid 30-9, connection b-9, coil 167, line 102. The "9" readout circuit for columns 1 and 2 differs from the above-traced circuit in omitting contacts 194a.

Between the units of dollars column and the dimes column of the total field of the bill, a tab space is preferably provided. The tabular spacing operation between these columns is automatically effected under control of the auto-type total emitter E-T when the brush thereof engages the "tab" spot of the emitter, in the same manner as explained in connection with the read out of the product through the product emitter E-P, the "tab" spots of the two auto-type emitters being connected to each other (see Fig. 12b).

After passing spot "1," the brush of emitter E-T engages a "reset" spot, establishing an auto carriage return circuit, which begins the same as the total auto type circuits and from the "reset" spot continues through connection b-61, the carriage return solenoid 30-CR (Fig. 12a), connection b-60, to line 102.

Total taking and resetting.—Between the "reset spot" of total emitter E-T and the reset magnet RM-T of the total bank is a pair of relay contacts 195a, which remain open when the key TK is operated to cause total taking operation without accompanying resetting. When total taking and resetting are both required, the total operation is initiated by depressing the total and reset

key TRK to close contacts TRK', forming the following circuit (begin with Fig. 12a):

Total and reset key circuit.—Line 101, connection b-44, contacts TRK', connection b-43 (continue with Fig. 12f), pick-up coil 195, coil 171, line 102.

The above circuit energizes coil 171 just as when the total key circuit was formed as a result of operation of the total key TK. All the total taking operations, described above as initiated by operation of the key TK, now take place as a result of the operation of key TRK to energize coil 171. In addition, however, the total and reset key circuit has energized pick-up coil 195. The latter thereupon closes contacts 195b to establish the circuit of holding coil 195' as follows (Fig. 12e):

Holding coil 195' circuit.—Line 101, total bank reset contacts RMa-T, contacts 195b, coil 195', line 102.

Coil 195' now remains energized until contacts RMa-T open during resetting of the total bank. Energization of coil 195' maintains contacts 195a (Fig. 12b) closed, so that when the brush of emitter E-T reaches the "reset" spot during readout of the total bank, the reset magnet RM-T is energized to cause resetting of the total bank.

Credit balance readout.—It has been assumed that the net balance standing in the total bank is a plus or debit balance. If the credits exceed the debits, then the net balance will be a credit or minus balance. The grand total, debit or credit, to be accumulated in the present case, is not to exceed eight denominational orders and is within the capacity of columns 1 to 8 of the total bank. It will be recalled that when a credit was entered in the total bank, a "9" was entered in column 9 of the bank. If the net balance is a debit total, then a carry-over will have been effected to column 9 to bring its reading to "0." If the net balance is a credit total, then the 9th column will read "9." When this is the case, the remaining columns of the total bank carry the complement of the credit or minus balance. This complement must be converted into the corresponding true number and typed as such in the total section of the bill.

In the same manner as explained for the debit total taking operations, the total relay coils circuit is formed, followed by the closing, through cam contacts R7 and 186d, of the credit balance control magnet 189 circuit (Fig. 12f). Magnet 189 closes the group of 189a contacts and also the pair of contacts 189b (Fig. 12b). Now, with the ninth column of the total bank reading "9," indicating a credit balance, the following circuit forms (Fig. 12b):

Credit balance pick-up coil 196.—Line 101, the common side of the 189a contacts, the left-hand pair of these contacts, a pick up coil 196, the + collector ring of column 9 of the readout commutator TRO, the + brush 51 thereof, the "9" digit segment 53 of the 9th column, through the connected row of "9" digit segments of the columns 8 to 3, the left side of contacts 194a, the "9" segments of columns 1 and 2, a wire 197, contacts 189b, a coil 198, line 102.

Coil 196 closes contacts 196a to energize the holding coil 196', as follows (Fig. 12e):

Coil 196' circuit.—Line 101, cam contacts R8, contacts 196a, coil 196', line 102.

The credit balance control magnet 189 is de-energized, and the credit balance pick-up coil 196 circuit broken, when cam contacts R7 (Figs. 11b and 12f) open, but coil 196' remains energized

and holds contacts 196a closed until contacts R8 open after the first or lowest order column of the total bank has been read out.

When the credit balance pick-up coil 196 circuit breaks, coil 198 is deenergized and its contacts 198a close. Since contacts 196a also are closed, the following circuit forms (Fig. 12e):

Inversion magnet.—Line 101, cam contacts R6, contacts 196a, 198a, in parallel through coil 194 and inversion relay magnet 193, line 102.

Magnet 193 shifts the center blades of the group of contacts 193a-0 to 9 (Fig. 12b), opening the normally closed side of these contacts which are in the debit total auto type circuits. The closing of the normally open sides of contacts 193a connects segments 53 of the readout commutator TRO to the complementarily related key solenoids 30, causing the complement of the credit balance in the total bank to be read out and typed as a true credit balance. Contacts 193a are shifted as a result of the energization of magnet 193 when contacts 198a close, which is timed by opening of cam contacts R7 to occur before cam contacts R8 close. When the latter cam contacts close, the total control magnet 190 circuit (Fig. 12f) is established to energize magnet 190 which closes the group of 190a contacts (Fig. 12b). Assuming for example, that column 8 of the total bank reads "6," the following circuit forms (Fig. 12b):

Credit total auto type circuit.—Line 101, contacts 83, contacts 117d, 191a, the brush of emitter E-T, the "8" spot thereof, the connected 164b contacts, the normally closed side of contacts 201a, the + collector ring of column 8, the + brush thereof, the "6" segment, the contacts 190a in series with the connected "6" segments, the lower, now-closed side of inversion contacts 193a-3, connection b-14 (continue with Fig. 12a), solenoid 30-3, connection b-8, coil 167, line 102.

This circuit causes typing of "3" as a result of the credit reading of "6" in column 8 of the total bank. In a similar manner, the "9" complements of values in all the other columns of the total bank, except the units order column, are read out and typed. The "9" credit value readout circuit of columns 8 to 3 proceeds from the "9" segment of column 3 through the lower, now-closed side of contacts 194b (coil 194 has been energized by the inversion magnet circuit), through contacts 190b, the lower, now-closed side of inversion contacts 193a-0, line 168 (turn to Fig. 12a), the center blade of contacts 167b, and from there either to the "0" or the space bar solenoid 30, depending on the condition of contacts 167b which, in turn, depends on whether a significant digit has been read out from a higher order column. Thus, the nine complement "0" of a "9" in columns 8 to 3 is normally read out by the above circuit. For a credit reading of "9" in column 2 (the tens of cents order), it is desired normally to type a "0," regardless of whether a significant dollars digit has or has not been printed. The "9" credit readout circuit of column 2 proceeds from the "9" segment of this column to the right, now-closed side of contacts 194a, through a wire 199, the wire 170 (turn to Fig. 12a), and connection b-11 to solenoid 30-0. In column 1, the units order column, the "10" complement of the credit value must be read out and typed. Thus, if the + feeler of column 1 is on segment 53-0, then "0" must be readout. When inversion magnet 193 was energized, it also closed the left side of contacts 193b and opened the right side, connecting the "1" spot of emitter E-T

to the minus collector ring of column 1 and disconnecting the "1" spot from the + collector ring of this column. The — brush, as explained hereinbefore, is one step behind the + brush. Thus, if the + brush is on "0," then the — brush is on the "9" segment (see Fig. 3a). The circuit for the units order complement of credit reading "0" is, then, as follows (Fig. 12b):

"0" units order credit readout.—Line 101, contacts 83, 117d, 191a, the brush of emitter E-T, the "1" spot, the left side of contacts 193b, the — collector ring of column 1, the — brush thereof, the "9" segments 53 of columns 1 and 2, the right side of contacts 194a, wire 199, wire 170, connection b-11, solenoid 30-0, connection b-10, line 102.

Similarly, any other credit value in column 1 is read out through the — brush of this column in order to provide the "10" complement thereof. For example, if the units order column + brush is on the "6" segment, the — brush is on the "5" segment. With the left side of contacts 193b closed, the readout circuit for the first column proceeds from spot "1" of emitter E-T through the left side of contacts 193b, to the — collector ring, the — brush, the segment "5," the connected points 190a, the now-closed, lower side of contacts 193a-4, connection b-15 (continue with Fig. 12a), solenoid 30-4, connection b-8, coil 167, line 102. As a result, the "10" complement, "4," of the units order credit reading of "6" is typed.

In reading out the "10" complement of the credit reading in column 1, the elusive one for this column has been taken care of. The reading out of "9" complements of the credit values in other columns has also been explained. However, if the units order reads "0," then the elusive one must also be added to the tens order, and if the tens order also read "0," then the elusive one must be added to the hundreds order, and so on. Thus, under the above conditions, the elusive one must be added not only to the units order but to all the orders to the left thereof and including the first one containing a significant figure, just as though the latter were really the units order. In other words, the first significant digit from the right and the "0" digits in all the orders to the right of this first significant figure must be read out as "10" complements, while the digits in the orders to the left of the first significant figure must be readout as "9" complements. For example, the real number corresponding to the complement of 99,082,000 is 009,18,000. When the complementary figure 99,082,000 is standing in the first eight columns of the total bank, then the ninth column also reads "9," manifesting a credit balance. With this complementary reading in the total bank, the ninth column commutator + brush 51 is on the segment "9"; in the eighth and seventh columns, the + brushes are on the segments "9" and the — brushes on the "8" segments. In the sixth column, the + brush is on segment "0" and the minus brush on segment "9"; in the fifth column, the + brush is on segment "8" and the — brush on segment "7"; in the fourth column, the + brush is on segment "2" and the — brush on segment "1"; and in the third, second, and first columns, the + brushes are on segments "0" and the — brushes on the "9" segments.

When the credit balance control magnet 188 was energized, as previously described, it closed the group of 189a contacts (located above the auto type emitter E-T, Fig. 12b). Between these 75 several contacts and the — collector rings of col-

umns 1 to 7 are elusive one pick-up coils 201, 202, 203, 204, 205, 206, and 207. Simultaneously with formation of the circuit of coil 186, traced before, through the left-hand pair of contacts 189a, the following parallel circuit is completed as a result of the — brush of the column 1 engaging the "9" segment (Fig. 12b):

Elusive one pick-up coil 201.—Line 101, the common of the 189a contacts, the first pair of 189a contacts from the right, pick-up coil 201, the — collector ring of column 1, the "0" segment thereof, wire 187, contacts 189b, coil 188, line 102.

Similarly, elusive one pick-up coils 202, 203, and 206, respectively associated with the second, third, and sixth columns, are energized as a result of their — brushes engaging "9" segments. The elusive one pickup coils 204, 205, and 207 are not energized because the — brushes of columns 4, 5, and 7 are not engaged with "9" segments. It may be noted that an elusive one relay coil is not provided for the eighth column because if this column reads "0" and the other columns to the right also read "0," then the net balance is zero, and means are provided, in that case, to prevent any auto typing operations, as will be explained later.

At this time, for the assumed example, the pick-up coils 186, 201, 202, 203, and 206 are energized and respectively close contacts 189a, 201b, 202b, 203b, and 206b (bottom of Fig. 12e). A 30 circuit thereupon is established from line 101, through cam contacts R8, contacts 189a, wire 208, contacts 201b, holding coil 201', to line 102. The circuit of holding coil 202' is formed similarly through serially connected contacts 201b and 202b, and for holding coil 203 through serially connected contacts 201b, 202b, and 203b. The circuit of holding coil 206' cannot form because the contacts 204b and 205b are open, breaking the connection between closed contacts 203b and 206b. Thus, energization is effected only of the elusive one holding coils which are related to the columns of the total bank which read "0" to the right of the first right hand significant figure. When cam contacts R7 open, the magnet 188 is deenergized, its contacts 189a and b open, and the elusive one pick-up coils are deenergized.

Coils 201', 202', and 203' open the normally closed, right sides of their respective contacts 201a, 202a, 203a and close the left sides, thereby disconnecting the + collector rings of columns 2, 3, and 4 from spots "2," "3," and "4" of emitter E-T and connecting the — collector rings of these columns to these emitter spots. The read out circuit for the column 4 proceeds, then, from spot "4" of the emitter E-T, through the left, now closed side of contacts 203a, the — collector ring of column 4, the — brush thereof, the segment 53-1 engaged therewith, the associated pair of contacts 189a, the now-closed, lower side of inversion contacts 188a-8, connection b-18 (continue with Fig. 12a), solenoid 30-8, connection b-8, coil 187, line 102.

Thus, with the credit value "0" in each of columns 1, 2, and 3, the credit digit "2" in column 4 is read out as its "ten" complement "8." The "0" in each of columns 1, 2, and 3 is read out through circuits such as traced previously through the "9" segments of these columns, with the difference for columns 2 and 3 being in the routing of the circuits through their — collector rings and — brushes.

Zero balance operations

When the balance in the total bank is zero and the operator, nevertheless, initiates total taking

operation, means are provided to prevent formation of any circuits through total emitter E-T. Thus, the first column of the total section will remain set at the typing position, indicating to the operator that the balance is zero. It will be recalled that the readout of a zero, when not preceded by a significant digit, from columns 8 to 3 of the total bank is routed through the normally closed side of contacts 187b to the space solenoid 30-SP to effect intraline or character spacing of the bill. When the balance is 1 to 9 cents, the "0" in column 2 is nevertheless readout into solenoid 30-0, as explained previously, to type "0" in the tens of cents column of the total section. However, when the balance is zero in all the columns, then the readout of zeros from any column, including cents columns 1 and 2 is prevented. Therefore, space bar operations will not occur and the first column of the total section will remain at typing position. Also, carriage return operation will be prevented and the total line of the bill will remain at the typing line.

To determine whether the balance is zero, a so-called zero test shot is made before the total readout begins at point "8" of a readout cycle (Fig. 11b). It will be recalled that when the carriage was tabulated to the total field and the total key depressed, the coil 187 circuit (Fig. 12f) was completed. Coil 187 closes contacts 187d and, when cam contacts R11 close, a circuit is formed through the "0" test multi-contact magnet 210, as follows (bottom of Fig. 12f):

"0" balance test magnet circuit.—Line 101, contacts R11, contacts 187d, plural coil magnet 210, line 102.

Magnet 210 operates its several relay contacts, and if columns 1 to 8 of the total bank all read "0," then the following circuit forms (start with Fig. 12a):

"0" balance detecting circuit.—Line 101, relay contacts 210a, wire 211 (turn to Fig. 12b), the first column "0" segment, the + brush engaged therewith, the + collector ring, contacts 210b, the + collector ring of the column 2, its + brush, the "0" segment of the column 2, contacts 210c, the "0" segment of the column 3, the + brush of column 3, its + ring, contacts 210d, the + ring of the column 4, its + brush, its "0" segment, the "0" segment of the column 5, its + brush, its + ring, contacts 210e, the + ring of the column 6, its + brush, its "0" segment, the "0" segment of the column 7, its + brush, its + ring, contacts 210f, the + ring of the column 8, its + brush, its "0" segment, contacts 210g, wire 212 (turn to Fig. 12e), coil 181, line 102.

As may be noted from Fig. 12b, contacts 210h, i, j, and k are, respectively, inserted between the "0" segments of the first and second columns, between the "0" segments of the third and fourth columns, between the "0" segments of the fifth and sixth columns, and between the "0" segments of the seventh and eighth columns of the total bank. When magnet 210 is energized, it opens these contacts 210h, i, j, and k, insuring the "0" balance detecting circuit being routed, seriatim, through the + collector rings of all the columns. If, for example, the "0" segments of the first and second columns were not disconnected by the opening of contacts 210h, then the circuit would go from the "0" segment of the first column directly to the "0" segment of the second column, and through contacts 210c to the "0" segment of the third column, thus skipping the "0" test for the second column.

When the "0" balance detecting circuit is

b-50 (turn to Fig. 12a), the dotted line position of switch SW-PR, connection b-52 (continue with Fig. 12e), coil 215, cam contact A12, line 101.

Coil 215 closes contacts 215a, in parallel with contacts RH_d, to form a circuit, similar to clutch circuit #1, through the clutch magnet 40 (Fig. 12f), setting the calculator shaft 36 in operation. The energization of magnet RM-P then causes resetting of the product bank.

If the switch SW-PR is thrown to alternative position while the calculator unit is effecting multiplication, the multiplication operation will be stopped immediately and the product bank reset. For this purpose, coil 215 closes contacts 215b (Fig. 12e), connecting the common of switch SW-#2 to the "4" spot thereof, as a result of which the release magnet SWR-2 circuit, in which coils 131 and 153 are included, is formed, causing restoration of the switch SW-#2 to home position, while the coil 131 opens contacts 131a common to the stick circuits of the retainer relay coils 114 (Fig. 12c). Thus, the value retaining means is cleared, and the multiplying operation, which requires energization of column shift magnets 128 (Fig. 12e) is interrupted. The resetting of the product bank is effected by the energized magnet RM-P. The purpose of throwing switch SW-PR during multiplying operation is to reset the product bank and clear the value retainer means upon discovering an error after multiplication has begun. If the error is discovered after multiplication has been completed but before the auto typing of the product has begun, then the coil 160 stick circuit will have been closed but the coils 149 and 161 circuit still will be open. Then, by operation of switch SW-PR, the product bank will be reset and, during the resetting operation, reset switch RM_a-P will open to break the coil 160 stick circuit (Fig. 12e), preventing the initiation of the auto readout of the product. 35

When resetting of the total bank is desired, the switch SW-TR (Figs. 1 and 12a) is closed, causing the following circuit to form (Fig. 12a):

Coil 206 circuit.—Line 101, connection b-54, the dotted position of switch SW-TR, connection b-53 (continue with Fig. 12f), coil 216, line 102.

Coil 216 closes contacts 216a, parallel with contacts 215a (Fig. 12f), to establish the clutch magnet circuit. The coil 216 also closes contacts 216b to form the circuit of reset magnet RM-T of the total bank, as follows (Fig. 12b):

Alternative total bank reset circuit.—Line 102, magnet RM-T, contacts 216b, wire 217 (turn to Fig. 12e), cam contacts A12, line 101.

Resetting of the total bank then is effected by energization of magnet RM-T.

The product and total banks may be reset simultaneously by moving switches SW-TR and SW-PR to dotted positions (Fig. 12a).

Error key control

The error key EK (Fig. 1) is used to clear the value retainer bank if an error is discovered in the manual typing within the quantity, price, or credit sections. The operation of the error key causes deenergization of any value coils 114 which may have been energized before the error key was depressed. The error key operation also causes the switch SW-#1 to be restored to home position. When the error key is depressed, it opens the normally closed left side of contacts EKa and closes the normally open side thereof (Fig. 12a). The opening of the normally closed side of contacts EKa breaks the value coil stick circuits which may have previously been formed,

deenergizing all the value coils 114. The closing of the normally open side of contacts EKa forms the following circuit (Fig. 12a):

5 *Release magnet SWMR-1 circuit #2.*—Line 101, connection b-34, the right, now closed side of contacts EKa, connection b-35 (turn to the bottom of Fig. 12b), the normally closed side of contacts RH_c, switch contacts SWa-1 (closed when the feeler of switch SW-#1 advanced from home position), release magnet SWR-1, line 102.

A parallel circuit is formed which proceeds from connection b-35 through coil 143 to line 102.

Energization of magnet SWR-1 restores switch SW-#1 to home position.

Coil 143 energized by the parallel circuit opens contacts 143a (Fig. 12e) in coil 111 circuit #2 causing opening of contacts 111a (Fig. 12a) in the key coils circuit, coil 140 circuit, and coil 120 circuit, preventing further entry of price values into the value retainer bank.

When the operator has already typed the price and quantity values and multiplication has begun but is not completed, the operation of the error key opens the stick circuits of the value coils, as explained above, causing contacts 114b (Fig. 12d) to open. Further, since magnet RH is deenergized, contacts RH_e in the circuit of magnet SWM-2 (Fig. 12e) reopen, prevent further advance of the switch SW-#2, and multiplication ceases. Contacts RH_d (Fig. 12f) open, breaking clutch circuit #1, and the cycles of shaft 36 stop when the clutch shunt circuit breaks. The product bank is then reset by operation of switch SW-PR.

If multiplication has been completed and the amount section of the bill not tabulated to typing position, then the depression of the error key is without effect. In that case, to rectify an error, the operator must move switch SW-PR to dotted position, causing the product bank to be cleared.

If an error is noted after the credit key is depressed, the opening of contacts EKb breaks the credit coils circuit which include contacts EKb (Fig. 12a). Deenergization of credit coils 150, 155, and 172 results. Also credit coil 163 circuit is broken by opening of contacts EKb.

If there has been no error in the typing of the factors involved in a debit product, but the credit key has been erroneously operated, then the depression of the error key, after multiplication is completed and before the amount section has been tabulated to typing position, or while its first column still is in typing position, breaks the credit coils circuits and permits the product to be typed in the amount section.

60 If an error is noted during the typing of a cash credit, the depression of the error key will open the circuits of the credit coils. Deenergization of coil 172 will permit contacts 172b in the main circuit of coil 111 (Fig. 12e) to open. As explained above, the coil 143 also will be energized to open contacts 143a in the coil 111 circuit #2. Thus, depression of the error key will prevent further entry of the credit amount into the value retaining means.

Column reduction

70 When the factors to be multiplied do not exceed five digits; say, two quantity orders and three price orders, then the product will not exceed five digits, and use may be made of the column reduction feature of the machine to save time in the product auto type and entry operations, and also, if the balance does not exceed five digits, in the total taking and typing operations. When

formed, coil 181 is energized, closing contacts 181b (Fig. 12e) to form a stick circuit for the coil through cam contacts R10, which remains in effect for the rest of the first readout cycle. During the succeeding readout cycles, the circuits of magnet 210 and of coil 181 are repeated.

Coil 181, upon energization, opens contacts 181a, in the common side of the total auto type circuits (see Fig. 12b). As a result, the space bar solenoid circuits, normally provided when the column preceding a significant figure reads "0," do not form, the automatic tabular spacing between the dollars and cents field of the "total" section of the bill does not occur, and the automatic carriage return is prevented. Consequently, the bill will remain stationary, with the left-hand column of the total section resting at typing position. As the carriage has not been tabulated, switch SW-#3 remains in position "10," coil 187 remains energized, and the clutch circuit is maintained through its contacts 187b, causing continuous running of the calculator unit. All these indications call the operator's attention to and manifest the fact that the balance reading is zero. This is of particular value when the indicator wheels 41 of the total bank are not visible to the operator.

It may be noted that the purpose of normally open contacts 210c between the "0" segments of columns 2 and 3 of the total bank is to disconnect the "0" segments of columns 8 to 3 from the "0" segments of columns 1 and 2, except when all the columns read "0" and the "0" balance detecting circuit forms. The purpose of the normal break between the "0" segments of the second and third columns is to cause a "0" in the tens of cents order or second column of the total bank to be read out and typed even if all the dollars columns read "0," provided, however, that there is a significant figure in the units of cents column. Thus, with all the dollars columns standing at "0" and the units of cents column having a significant figure, the contacts 187b (Fig. 12a) will be in normal condition with its right-hand side closed, routing the "0" readout circuits of the dollars columns to the space bar solenoid 30-SP. However, if the second column also reads "0," the following readout circuit will be established (Fig. 12b):

"0" debit readout of second column of total bank.—As in the other total auto type circuits to spot "2" of the emitter E-T, the normally closed side of the connected 201a contacts, the + ring of the column 2, the + brush thereof, the "0" segment thereof, normally closed contacts 210h, the "0" segment of the units column, wire 211 (turn to Fig. 12a), contacts 180c of the now-energized total control magnet 180, the normally closed side of inversion relay contacts 183c, connection b-11, solenoid 30-0, connection b-8, coil 187, line 102.

Thus, the lack of a significant figure in the dollars columns of the total bank does not prevent the readout and typing of a "0" in the dimes column preceding a significant figure in the units of cents column.

The "0" debit readout circuit of column 1 of the total bank is through a similar circuit, extending from total emitter spot "1," through the normally closed side of inversion relay contacts 183b to the + collector ring of column 1, the + brush and "0" segment thereof, wire 211, and from there on as in the preceding circuit.

When the total bank carries a credit or minus balance, then the inversion relay magnet 183 is

energized during total readout, and contacts 181b and c are in shifted condition, preventing formation of the above "0" debit readout circuits through columns 1 and 2. The "0" credit readout circuit of column 1 has been traced previously. If column 1 has a credit value of "0," then the tens complement of the credit value in column 2 also is read out, and if column 2 reads "0," then typing of a zero in the dimes column of the total section results, as previously explained. However, if column 1 has a significant digit, then the "9" complement of the column 2 value is read out, and if column 2 reads "0," the following circuit forms (Fig. 12b):

"0" credit readout of column 2 of total bank.—As in the previous total readout circuits to emitter spot "2," then through the normally closed side of contacts 201a, the + collector ring of column 2, the + brush thereof, the "0" segment engaged thereby, contacts 210h, the "0" segment of column 1, wire 211 (turn to Fig. 12a), total relay contacts 180c, the right now-closed side of inversion relay contacts 183c, a wire 213 (return to Fig. 12b), the jumper to the lower, now-closed side of inversion relay contacts 183a-8, connection b-20 (continue with Fig. 12a), the key solenoid 30-9, connection b-8, coil 187, line 102.

Thus, when column 1 has a significant credit digit and column 2 reads "0," then the "9" complement of the column 2 reading is typed.

Regarding successive discounts.—As explained before, in taking successive discounts (see lines 8 to 11 of Fig. 13), the amount on which the discount is to be taken is the net balance, and it is desired to print this balance in the total section along the same line as the item which has been previously entered. For this purpose, the total key TK is operated before tabulating to the amount or credit section; the total key circuit is formed, energizing coil 171 to open contacts 171a (Fig. 12a) in the auto carriage return circuit during readout of the product. Thus, the same line of the bill remains at the typing line, and when the total section is tabulated to typing position, the total or balance is automatically typed therein, in the manner explained before. During the total readout, the auto carriage return circuit is formed, coil 171 having meanwhile been de-energized. The operator then types the discount percentage in the quantity columns and the balance, read from the preceding line, in the price columns and proceeds with the discount operation, which is performed in the same manner as described before. If the next line is also a balance discount operation, the operator, before tabulating the credit section of the bill to typing position, again depresses the total key TK, thus preventing auto carriage return during the cycle of the product auto type emitter E-P, in the manner explained previously.

The reset switches

In addition to the automatic reset provided through the auto type emitters, the product and total banks may be reset at any time, at the will of the operator, by throwing the switch SW-PR (Figs. 1 and 12a) to dotted line position (Fig. 12a) when it is desired to reset the product bank, closing the switch SW-TR when the total bank is to be reset, and both switches when both banks are to be reset.

When switch SW-PR is closed, the following circuit forms (begin with Fig. 12b):

Alternative reset of product bank.—Line 102, product bank reset magnet RM-P, connection

making use of the column reduction means, the tab stops are set in accordance with the reduced amount, credit, and total fields to be utilized. For instance, if the debit, credit, or total values are never to exceed five digits, a bill sheet with five columns, three for dollars and two for cents, in each of the amount, credit, and total sections may be used. The tab stops will then be set so that operation of the tab key, after the description is typed, will bring the hundreds dollar column of the amount section to typing position, the next tab key operation will bring the cents field of the amount section to typing position, a further tab operation will bring the hundreds of dollars column of the credit section to typing position, the next tab key operation will bring the cents field of the credit section to typing position, and a still further operation of the tab key will bring the hundreds column of the total section to typing position. To initiate column reduction operation, the column reduction switch SW-C (Figs. 1 and 12a) is closed. The quantity and price factors are typed in the same manner as before, causing setting up of the value coils 114 and the corresponding 114b contacts, space bar operations being effected for the left hand columns of the quantity and price fields in which typing is not to be effected. The multiplication will take place as before. When the carriage is tabulated to the amount section, the coils 149 and 161 circuit will be formed and contacts 149d (Fig. 12f) closed. With the column reduction switch SW-C closed, the following circuit will form (Fig. 12f):

Column reduction magnets.—Line 101, contacts 149d, connection b-82 (turn to Fig. 12a), switch SW-C, connection b-63 (return to Fig. 12f), column reduction magnets 164 and 126, line 102.

Magnet 126 opens contacts 126a in the main circuits of the first five left hand columns of value coils 114 (Fig. 12c) and closes contacts 126b. The magnet 164 closes contacts 164c (Fig. 12c) connecting segments "1," "2," and "3" of switch SW-#1, now disconnected by opening of contacts 126a from the first three left hand columns of coils 114, to the fourth, fifth, and sixth columns of coils 114 from the left. Contacts 126b similarly connect segments "4" and "5" of switch SW-#1 to the seventh and eighth columns of coils 114, from the left. Thus, when switch SW-#1 is in positions "1" to "5," inclusive, it conditions the fourth, fifth, sixth, seventh, and eighth column of coils 114 from the left to receive entries.

The magnet 164 also opens contacts 164a of the product auto type circuits for the three left-hand columns (see Fig. 12b), in effect reducing the size of the product bank read out commutator to five columns. It is understood that since the product does not exceed five digits, the three left-hand columns stand at "0." The product auto typing circuits will read out the five right hand columns of the product bank, and the resulting operation of the digit keys will set up the five right-hand columns of value coils 114 and corresponding columns of 114b contacts. The product will then be entered, as before, through the 114b contacts, into the total bank.

If the item is a simple or cash credit, the depression of the credit key will result in closing of the credit coils circuit and credit coil 172 will close contacts 172d (Fig. 12f), which shunt contacts 149d and replace the latter in forming the circuit of column reduction magnets 126 and 164. The same three column reduction shift will take

place as when a debit amount was involved, although the column reduction shift is needed only for the connections between switch SW-#1 and the value retainer bank.

When total taking operation is initiated, the total relay coils circuit is established, and energization of total relay coil 188 (Fig. 12e) closes contacts 188a, in parallel with contacts 149d and 172d, forming the circuit of column reduction magnets 126 and 164. Magnet 164 opens contacts 184b in the total auto type circuits of the eighth, seventh, and sixth columns of the total bank, effectively reducing the size of the total bank to the five right hand columns, so that during total taking operation only the latter columns of the total bank will be read out.

As explained hereinbefore, during entry into the totalizer ACC-T of a computed or simple credit, complement "9" is entered into any order 20 of the totalizer when its related column of value retaining relays 114a, b has not been set up. This "9" complement entry is effected, as described before, through the normally closed pair of contacts 125c, 133c, etc. shown in Fig. 12d above the value representing contacts 114b. When none of the contacts 114b of a column have been operated, the normally closed contacts above the value contacts of the column remain closed. In column reduction, the three highest orders of 30 the value retaining columns are not set up to digital values. Hence, during entry of a credit into the totalizer, complements "9" will be entered through contacts 125c, 133c, and 134c, severally, into eighth, seventh, and sixth orders. The "9" complement will be entered as before into the ninth order. Thus, through the usual transfer means between the orders and by reason of entry of "9's" in the four higher orders of the totalizers, a positive balance will be manifested by the ninth order standing at 0 while a negative balance will be manifested by the ninth order standing at 9. Accordingly, the ninth order of the totalizer will function the same way with column reduction as without column reduction to determine whether the balance is to be recorded as the number registered on the totalizer or as the complement of this number.

By reducing the effective size of the total bank and the product bank to five columns, the space bar solenoid 30-SP will not be energized as a result of the "0" readings in the three left-hand columns, thus permitting the left-hand, hundreds dollar order columns of the amount, credit, or total section of the bill to remain set in the position to which the tabular spacing operation has brought them, ready to receive the digit read out of column 5, or the hundreds dollar order, of the total or product bank.

While a three column reduction has been considered, provision may be made for alternative column reduction of more or less columns.

It should be noted that the quantity and price fields are not reduced in size, in order to take care of the entry of a discount item. The discount percentage and the amount on which the discount is given are entered in the same manner as before and cause the eight columns of the value retainer bank to be set up. Multiplication then proceeds, and since the discount relay contacts 165a (Fig. 12b) have been shifted, the true discount product is read out of columns 8 to 4 through spots 5 to 1 of emitter E-P. Also, with column reduction contacts 164a open, the wiping by the feeler of emitter E-P of spots 8, 7, and 6 does not cause space bar operations. The total

entry is effected in the same way as for the other column reduction items.

While there has been shown and described and pointed out the fundamental novel features of the invention as applied to a single modification it will be understood that various omissions and substitution and changes in the form and details of the device illustrated and in its operation may be made by those skilled in the art without departing from the spirit of the invention. It is the intention, therefore, to be limited only as indicated by the scope of the following claims.

What is claimed is:

1. The combination with typing means, including digit type-actions and a work sheet support with the type-actions and support having letter-spacing movement relatively to one another, for successively typing the digits of a plurality of factors, each being a multidigit number, of a succession of orders of digit storage devices, means controlled by the typing means concomitantly with typing of the digits for successively entering the digits of the multidigit factors into the orders of storage devices, multiplying means, including means for coaxing with the storage devices, for multiplying the factors stored therein, a control device operatively connected with the last digit storage order so as to be automatically rendered effective concomitantly with typing of the last digit of the last multidigit factor and entry of said last digit into the storage orders, and means controlled by the control device, when rendered effective, for automatically initiating operation of the multiplying means to multiply the stored factors.

2. In combination, digit keys, a succession of value storage orders of digit relays, circuits controlled by successive operation of the keys for successively operating the relays of one order after another according to the digits of a plurality of factors, multiplying means, including column shift means and means controlled thereby for coaxing with the operated digit relays, for multiplying the factors, product entry circuits closed by the multiplying means, a product accumulator with entry means therefor controlled by the entry circuits to cause the accumulator to form the product of the factors, and relay means operatively connected to the storage order which stores the last digit of the factors for automatically initiating operation of the multiplying means upon operation of a digit relay in the latter storage order.

3. In combination, column-by-column recording means, including digit recording elements and related operating devices, for successively recording digits of a plurality of factors in columns of a work sheet, a succession of orders of digit storage relays, means controlled by said operating devices during recording of the digits for successively setting up relays of the orders in succession to store the digits of the plurality of factors, multiplying means including a cyclically operating emitter and denomination shifting means coaxing with the relays for closing differentially timed value entry circuits, means for initiating operation of the multiplying means after the storage relays have been set with the plurality of factors, a product accumulator controlled by the entry circuits to form the product of the factors, a cyclically operated readout emitter, product readout circuits successively closed under joint control of the readout emitter and accumulator, means controlled by the readout circuits for automatically operating the recording

means to record the product, digit by digit, in successive columns of the sheet, means for effecting concurrent cyclical operation of both aforesaid emitters, and means controlled by the multiplying means for preventing the readout emitter from controlling closure of readout circuits before multiplication is completed and enabling the readout emitter to become effective to cause closure of the readout circuits after completion of multiplication, with the readout emitter by its rate of operation determining the rate of column by column recording of the product digits.

4. In combination, column by column recording means, including digit recording-actions and a work sheet support and spacing means for effecting relative movement between the sheet support and recording-actions to bring a predetermined field of columns to recording position, value storing means having a succession of orders of digit storage devices, means controlled by the digit recording-actions concomitantly with recording of the digits for setting up the storage orders in succession according to the digits of the factors, multiplying means controlled by the storage devices for multiplying the factors, means for rendering the multiplying means effective after the last digit of the factors has been recorded and set up in the value storage means, a product accumulator controlled by the multiplying means to form the product of the factors, readout means controlled by the product accumulator for automatically operating the recording-actions to record the product digit by digit in said predetermined field of columns of the work sheet, a control device operated under control of the multiplying means upon completion of multiplication, another control device operated under control of the spacing means upon spacing of the predetermined field of said sheet to recording position, and means under joint control of both said control devices for automatically rendering the readout means effective to read out the product.

5. In combination, recording means, including digit recording-actions, a sheet support cooperative therewith, and column spacing means, for successively recording digits in a series of columns of the sheet, a space operator for operating the column spacing means without accompanying recording-action, a series of value retaining orders corresponding to the series of columns, each order having a plurality of settable digit retaining devices, means controlled by the recording-actions concomitantly with recording of digits in said columns for selecting corresponding digit retaining devices of the orders for operation, means for successively correlating the value retaining orders with the columns brought to recording position to cause the selected devices of orders corresponding to columns in which digits are recorded to be set up in one such order after another to represent the digits typed in the corresponding columns, means controlled by each operation of the digit recording-actions and of the space operator for stepping the correlating means from one order to the next whereby correlation between the orders and the corresponding columns is maintained, and means effective upon the setting up of the last order of the series according to a digit for restoring the correlating means to initial condition.

6. In combination, recording means, having a set of digit recording-actions and a sheet support with the support and recording-actions having column spacing movement relative to one another, to record digits of a plurality of factors

successively in columns of the sheet, successive orders of digit storage devices, means controlled by the recording-actions during recording of the factors for entering the digits of the factors successively in the orders of the storage devices, multiplying means operable after all the factors have been entered in the storage orders for effecting multiplication of the factors under control of the storage devices, a product register controlled by the multiplying means to register the product of the factors, a control device operated under control of the multiplying means upon completion of multiplication as a manifestation of the completion of the multiplication, means operated by said control device for automatically clearing all the orders of storage devices of their entry when multiplication has been completed and the product registered in said register, and means thereafter controlled by the product register for operating the digit recording-actions to cause recording of the product digit by digit in columns of the sheet and concomitantly to cause the product digits to be entered successively in the orders of the storage devices.

7. In combination, column by column recording means, including digit recording-actions and a sheet support, for recording digits successively on the sheet, a single value representing structure with denominational related orders for representing a value which may be of one or another class, means coacting successively with the orders of the single value representing structure for automatically operating the recording-actions to record a total, digit by digit, in accordance with and as determined by the represented value, a controller to manifest correlation of one or another field of columns of the sheet with the recording-actions, each field adapted to receive a value of a different class, enabling means under control of the controller for enabling the second mentioned means to be effective when one or the other of the fields is correlated with the recording-actions, a device to be operable to signify that the represented value is of a particular class, and means controlled by said device, when operated, for causing the enabling means to be effective under control of said controller only when the field for receiving a value of the latter class is correlated with the recording-actions.

8. In combination, a typewriter having means, including digit type-actions and an intraline sheet support cooperative therewith, for typing values, digit after digit, on the sheet, a bank of value retaining devices, means controlled by operation of the digit type-actions, when typing a plurality of factors, for setting up the devices to represent the factors, computing means, including multiplying means and a product accumulator, operative connections between the bank of devices and the computing means for causing the computing means to form the product of the factors represented by the devices, means for completely clearing the devices of their set up after the product is formed, means controlled by the product accumulator for automatically operating the digit type-actions to type the digits of the product in succession, means for rendering the value retaining devices effective to be set up by the operation of the type-actions during the typing of the product, a totalizer, means for breaking the connections between the computing means and said retaining devices and rendering alternative connections effective between the retaining devices and the totalizer, and means coacting with the bank of devices according to their

product setup for entering the product, through the alternative connections, into the totalizer.

9. In combination, typing means, including digit type-actions, a sheet support, and intraline spacing means, for typing a plural order value digit by digit, in descending order progression, in a field of columns, each of which corresponds to one denominational order, value representing means having a succession of digit registering orders corresponding to the columns of the field, readout means for reading out said orders of the registering means, in descending order progression, to automatically control the type-actions for typing the digits registered in the orders which are read out, selectively conditionable operative connections between the orders of the registering means and the readout means conditionable in one way to cause typing in said columns under control of the corresponding orders of the registering means and alternatively conditionable in another way to cause typing in lower order columns under control of higher orders of the registering means and for causing operations of the intraline spacing means under control of the readout means to effect column spacing between the sheet support and the type-actions prior to the reading out of the first of the said higher orders of the registering means, and control means for determining the condition of said connections.

10. In combination; a typewriter having means, including digit type bars and related digit keys and an intraline spacing support for a work sheet, for typing a plural order value, digit after digit, in a plural column field of the sheet, value representing means having a plurality of digit representing orders, readout means including individual connections between the orders of the representing means and the readout means, for reading out the digital values of the several orders in succession, means controlled by the coaction of the readout means with the orders of the representing means representing zero preceding the first significant figure for effecting intra line spacing of the work sheet, a capacity reduction controller, and means operated by said controller for disabling the connections between the readout means and a number of the higher orders of the representing means so as to suppress intra-line spacing under control of said higher orders and to cause operation of the typing means to type in said sheet field under control of the remaining orders of the representing means.

11. In combination; typing means for typing a plural order value, digit after digit, on a sheet and including intra-line spacing means for the sheet operative by itself and also as an automatic accompaniment to the typing of a digit, plural order value representing means, readout means coacting with the value representing means, means controlled by the readout means for automatically operating the typing means to type the value, digit by digit, represented in the orders of the representing means, means controlled by the readout means upon reading out a zero preceding the first significant figure for operating the intra line spacing means to effect spacing of the sheet unaccompanied by typing, means acting before operation of the readout means for detecting a zero in all orders of the representing means, and means controlled by the zero detecting means for rendering the readout means ineffective to cause operation of the intra line spacing means.

12. A calculating machine having column by column recording means, including digit recording-actions and a sheet support with the actions and support having relative column spacing movement, for recording the digits of factors digit by digit in columns of the sheet on said support, a bank of value representing means, means controlled by the digit recording-actions upon their recording of the digits of the factors for setting the value representing means to represent the factors, multiplying means coacting with the value representing means to multiply the factors, a product accumulator controlled by the multiplying means to form the final product of the factors, means for reading out the final product from the accumulator, means controlled by the reading out means for automatically operating the digit recording-actions to cause the final product to be recorded, digit by digit, in columns of the sheet and concomitantly with the recording of the product to set the bank of value representing means to represent the product, a totalizer for totaling a plurality of successive final products, and means controlled by the value representing means according to the final product setting thereof for entering this product in the totalizer.

13. The machine as defined in claim 12, and including means to determine completion of multiplication of the factors, means to determine a particular column position of the sheet with respect to the recording-actions, and means jointly controlled by both determining means to render the reading out means effective to read out the product and cause automatic operation of the digit recording-actions to record the product in a particular field of the sheet starting with the said particular column.

14. The machine as defined in claim 12, and including means for determining completion of multiplication of the factors, means for determining a particular column position of the sheet relative to the recording-actions, cyclically operating means for operating the reading out means, a motor, clutching means between the motor and cyclically operating means, and means jointly controlled by both determining means for causing the clutching means to take effect to operate the cyclically operating means and for rendering the reading out means effective upon operation thereof by the cyclically operating means to read out the product and cause automatic operation of the recording-actions to record the product in a particular field of the sheet starting with said particular column.

15. A calculating machine having column by column recording means including digit recording-actions and a cooperative sheet support with means for column spacing the sheet support and recording-actions relatively to each other, a plurality of orders of value representing and storage relays, circuit controlled by successive operation of the digit recording-actions for setting the storage relays order after order according to desired digits, differentially actuatable entry receiving means, cyclic operating means, entry control means concurrently coacting with a plurality of orders of the storage relays according to their setting for coupling the entry receiving means to the cyclic operating means for differential cyclic times to receive value entries corresponding to the differential cyclic times, a motor, clutching means intermediate the motor and the cyclic operating means, and means, including a control device operatively connected to the stor-

age order which stores the last digit and operated upon the setting up of the latter order of storage relays according to a digit for rendering the clutching means effective to drive the cyclic operating means and to render the entry control means operative to control differentially timed coupling of the cyclic operating means to the entry receiving means.

16. A calculating machine having column by column recording means including digit recording-actions and a cooperative sheet support with column spacing means for spacing the support and recording-actions relatively to each other, a plurality of orders of value storage relays, circuits controlled by the recording-actions for setting the storage relays order after order according to a plurality of factors to be multiplied by one another, multiplying means including an emitter, with a cyclically rotating circuit closing device, for coacting with the storage relays to close value entry circuits, a product accumulator, means controlled by the entry circuits to enter values into the accumulator to form the product therein, a motor, clutching means, means actuated by the motor through the clutching means for effecting cyclic rotation of the circuit-closing device, and means operatively connected to the storage order in which the last digit of the factors is stored and controlled by the setting up of the last named order of value storage relays with the last digit of the factors for rendering the clutching means effective.

17. In combination, recording mechanism to record an amount and including digital value selector elements, a denominational order amount register, means to readout the register orders in succession, means controlled by the readout means for effecting successive operations of said elements to control the recording mechanism for the recording of the registered amount, a plurality of series of value storage relays, circuits controlled by said elements upon their successive operations for setting the plurality of series of storage relays successively according to the registered amount, a totalizer, means controlled by the storage orders for entering the stored amount in the totalizer, a control relay operatively connected to the last storage relay series set with a digital value and operated upon the setting of the latter series, and means controlled by said control relay for rendering the entering means effective.

18. In a machine in which line spacing means is provided; the combination of typing means to type amounts digit by digit in successive lateral fields of columns of a work sheet, a first amount register of which the registered amount is to be typed in one said lateral field, a second amount register of which the register amount is to be typed in a following lateral field, means for reading out the first register to cause operation of the typing means to type the amount derived from the first register in the related field, means normally effective after typing of the last digit of the latter amount for causing operation of the line spacing means to line space the sheet, means to select the second register to be read out, means controlled by the selecting means to prevent said line spacing operation, and means for reading out the second register when selected to cause operation of the typing means to type the amount derived from the second register in the said following field of the sheet and along the same line as the recorded amount read out from the first register.

and successively to type the result amount, digit by digit, in either of said fields, means for automatically bringing about operation of the reading out means and including means for automatically signifying completion of the setting of said value representing means, and means, apart from the latter manifesting means, for signifying the arrival of either field in typing position, and a class controller operable before either field is in typing position for selecting one of said fields to the exclusion of the other to be typed in with the result amount.

26. In combination, column by column recording means, including digit recording actions and a work sheet support and spacing means for effecting relative movement between the sheet support and recording actions to bring a predetermined field of columns to recording position, value storing means having a succession of orders of digit storage devices, means controlled by the digit recording actions concomitantly with recording of the digits for setting up the storage orders in succession according to the digits of the factors, multiplying means controlled by the storage devices for multiplying the factors, means for rendering the multiplying means effective after the last digit of the factors has been recorded and set up in the value storage means, a product accumulator controlled by the multiply-

ing means to form the product of the factors, readout means controlled by the product accumulator for automatically operating the recording actions to record the product digit by digit in said predetermined field of columns of the work sheet, a control device operated under control of the multiplying means upon completion of multiplication, another control device operated under control of the spacing means upon spacing of the predetermined field of said sheet to recording position, and means under joint control of both said control devices for automatically rendering the readout means effective to readout the product, said readout means including an emitter having successive column positions for successively closing product readout circuits under control of successive orders of the product accumulator, cyclically operating means for effecting cycles of operation of the emitter, and means operated by the cyclically operating means for preventing the readout means from being effective during a cycle of the emitter in which the second control device has been operated within a predetermined interval preceding the point of the cycle at which the emitter is in first column position.

CLAIR D. LAKE.
FRANCIS E. HAMILTON.

19. In a calculating machine in which a result amount of either of two classes is obtained by calculating operations, the combination of recording elements to record the result amount in either of two lateral fields of a work sheet, a work sheet-supporting carriage movable laterally to locate either said field in recording position, value representing means settable under control of the calculating means to represent the result amount, means controlled by the value representing means for operating the recording elements to record the result amount in either of said fields, means for automatically bringing the second named means into play to cause the recording of the result amount and including means for automatically signifying completion of the setting of said value representing means, and separate means for signifying the arrival of either field in recording position, and a class controller manually operable before either field is in recording relation for selecting one of said fields to the exclusion of the other to receive the record of the result amount.

20. In combination, a recording unit having digit recording elements and digit selectors therefor to record an amount in successive columns of a field of a work sheet, an amount register having a plurality of digit representing orders, readout means, including individual connections between the orders of the register and the readout means, for reading out the digital values of the several orders in descending order succession, said connections being selectively conditionable in one way to connect the readout means to the register orders so as to start reading out the representing means with a predetermined higher order and conditionable in another way to cause the readout means to start reading out the register with a lower order than the said predetermined higher order, a register capacity controller, means under control of said controller for determining the condition of said connections, and means controlled by the readout means according to the condition of the connecting means for causing successive operations of said digit selectors in accordance with the values represented in the register orders connected to the readout means.

21. In combination, digit selecting elements, amount storing means including denominationaly related digit storage orders, means for correlating the elements with the orders in descending order succession beginning with a particular order, means to cause the elements upon successive operations to set the correlated orders in descending order succession to store an amount, a capacity controller, and means under control thereof for causing the correlating means to start the correlation between the orders and the elements with a different order than said particular order whereby an amount is stored in different orders of the storing means.

22. In a combined typewriter and calculating machine in which carriage return mechanism is provided for line spacing and returning the paper carriage of the typewriter, the combination with the typing elements for typing amounts, digit by digit, on said paper during forward travel of the carriage, of two amount registers, means for reading out one said register to cause operation of the typing elements to type a total, derived from this register, digit by digit in one lateral field of the paper, means normally effective after typing of the last digit of said total for causing operation of said carriage return mechanism, means to select the other one of said registers

5 to be readout, means controlled by the selecting means to prevent said operation of the carriage return mechanism, and means for reading out said other one of the registers, when selected, to cause operation of the typing elements to type a total, derived from the latter one of the registers, digit by digit, in a field of the paper laterally following the first mentioned field, whereby the two totals may be typed along the same line of the sheet or, in the absence of selection of the said other one of the registers, the first mentioned total may be typed and the carriage return mechanism operated following typing of the last digit of the latter total.

23. In a calculating machine, denominational orders of digit relays, supplemental relays in a normal condition, one supplemental relay for each order of digit relays, means for setting some of the digit relay orders according to an amount and concomitantly altering the condition of the associated supplemental relays, while others of the digit relay orders remain unset and the supplemental relays associated therewith remain in their normal condition, multi-order entry receiving means, and means coacting with the digit relay orders for entering the complement of said amount in the entry receiving means and including means coacting with the supplemental relays remaining in normal condition for entering complements of zero in orders of the entry receiving means related to the orders of the unset digit relay orders.

24. In a calculating machine in which multiplication is effected by over and over addition of a multiplicand for a number of cycles equal to the value of a multiplier digit, the combination of a cycle counter, cyclically operating entry means tending to advance the counter one unit for each cycle, column shift magnets, each related to one order of a multiplier factor, means controlled by each magnet when energized for rendering said entry means effective to advance said counter, a stepping switch, means for advancing said stepping switch under control of the cycle counter when the number of cycles of multiplicand addition equals the value of a multiplier digit, plural order digit representing means, supplemental, selectively conditionable devices, each related to one order of said representing means, means for setting the orders of the representing means to represent multiplier digits and concomitantly altering the condition of the related devices, means for skipping setting operation for an order of the representing means thereby leaving the related device in unaltered condition, and circuits for said column shift magnets including the stepping switch and contacts selectively closed or opened according to altered or unaltered condition of the said devices, respectively, whereby the magnet related to a skipped order of the multiplier representing means will remain deenergized and the entering means will be ineffective to advance the cycle counter under control of this magnet.

25. In a calculating machine in which a result amount of either of two classes is obtained by calculating operations, the combination with a typewriter, including digit type-actions and a cooperative laterally traveling sheet-supporting carriage, for typing the result amount in either of two lateral fields of the sheet, of value representing means settable under control of the calculating means to represent the result amount, means for reading out the value representing means to operate the type-actions automatically
